UNITED STATES PATENT OFFICE

2,022,870

METAL CLAD SWITCH GEAR

Allen M. Rossman, Chicago, Ill., assignor to
 Rossman, Sargent & Lundy Patents Corpora-
 tion, a corporation of Illinois

Application October 6, 1930, Serial No. 486,685

47 Claims. (Cl. 175—298)

The present invention relates, generally stated, to equipment for generating and for distributing electric power, and is particularly concerned with bus and switch station equipment and with improvements in metal clad switch gear.

The invention represents a development in the construction of bus and switch stations which meets and conforms to the demands of manufacture, service, operation and maintenance of modern installations. It will be advisable to review briefly the background of prior art in order to provide a basis for a better understanding of the present case.

The generation of electric power in great quantities, and inter-connection of power systems, have increased the difficulties confronting the engineer who attempts to solve the problem of designing switching and station equipment which combines all the necessary and desirable features demanded by the various factors and conditions which have to be considered. These factors and conditions are presented chiefly by the requirements of manufacture, installation, safety, reliability of operation, and ease of maintenance of the equipment. The factor of safety must be considered in connection with the dangers which are present in a switch or bus station. The danger of interphase short circuits and hazard to life in switch houses, stations or switch yards is the most prominent and has been greatly increased with the increase of capacity of an electric generating or transmitting equipment.

Several systems have been developed and are being used, all intended to meet the above requirements, and particularly to combat the danger of interphase short circuits. These systems proceed mainly on two lines of thought. One proposes the enclosure of live parts in cast metal compartments, and the other proposes to segregate the live parts in space.

The first construction is represented by the Reyrolle system developed abroad, and the second is embodied in the Jamieson system developed in the United States.

In the Reyrolle or armored system the buses are disposed in rigid cast metal housings or compartments containing insulating compound. The structure is relatively expensive, has great weight and is of ponderous size. The cost of an installation of this type increases, of course, with the current capacity. The solid compound is unsuitable for high tension protection; it tends to break down and is not self healing as would be a fluid. The use of fluid insulation, however, is not practicable in this system.

The Jamieson system which, as has been said, proceeds upon the theory of segregating the various apparatus and conductors of common phase, requires considerable space and is unwieldy. More space and more volume is required with increased voltage. The live parts are exposed, which, in an outdoor installation is not desirable.

The system which I have developed provides individual insulation about all live parts. The phase conductors are disposed in individual 10 sheathing or tubing filled with self healing insulating oil. The system comprises a structural framework. Supported on this framework, in elevated position, are the phase conductors disposed in individual sheathing, junction boxes 15 for making connections between the phase conductors and certain apparatus, and the various equipment, such as oil circuit breakers, transformers, switches, and the like.

The required space is reduced to a minimum 20 while structural strength is effectively maintained to prevent the transmission of physical force from one sheathed conductor to an adjacent piece of apparatus. Free atmosphere and ground intervenes between all phase conductors of dif- 25 ferent phases.

The system disclosed in this case distinguishes over all other power systems by insulating all live parts. It distinguishes from the Reyrolle construction by individual fluid insulation and 30 spacing between the insulated, metallically sheathed conductors. It distinguishes from the Jamieson construction by a decrease in volume and space and complete sheathing of all live parts. It is more compact and more flexible; 35 cheaper in production and installation; more efficient in operation; and more reliable in service as well as safer and easier in maintenance.

Modern practice of designing power stations also demands that attention be paid to the question of standardization and labor saving. It is the aim of manufacturers to complete a station as nearly as possible in the factory, finishing all component parts and shipping these parts to the place of installation in a condition which requires 40 little field work.

The system disclosed by my invention is readily adapted to standardization of parts. As a matter of fact, standardization has been made possible by the unit type construction which I propose, 50 to a degree which could not be achieved by any other system.

The structure is raised to overhead position which accomplishes numerous desirable results. In the first place, the conductors and apparatus 55

- in overhead position on a structural framework of simplified character, having means for insulating the column bases of the structural framework to ground;
- 5 A third object is concerned with a novel method and with novel means for terminating the cables at the ground level or at a point between the ground and the structural framework;
- 10 A further object has to do with a novel method and novel means for making connections between junction boxes at bay divisions;
- 15 Still another object has to do with novel methods and means for joining the bus enclosing tubes or pipes at the bay divisions in insulated relation from each other, together with valve means for filtering and for circulating oil through the bus enclosure sections and through the coupling;
- 20 A further object is concerned with a novel means for coupling bus sections;
- 25 Another object, in conformance to the thought of standardization, aims at provisions for the convenient removal of cables at current transformer boxes, presenting the possibility of installing cables from either side of the current transformers, thus making it possible to employ a bay unit for either one of two different functions within a station;
- 30 A further object is concerned with designing the connections for the current transformer boxes so that the current transformer is placed, in one embodiment, in a plane below a cross conductor, and in another embodiment in the same plane as the cross conductor, the latter structure giving the possibility to reduce the dimensions of the current transformer enclosing box;
- 35 Still another object relates to a novel arrangement of junction boxes on the structural framework, particularly illustrated with reference to that section of the switching equipment which contains the circuits for the reactors;
- 40 A further object has to do with simplifications in the structural framework at the bay division;
- 45 Another object is concerned with the placing and attachment of the cable entrance boxes or pot head boxes to the structural framework of the various bays, such as the sectionalizing, the feeder, the generator, and the reactor bay, in such a manner as to present not only a pleasing exterior but to economize space and to retain 50 utmost efficiency;
- 55 Still another object has to do with the provision of novel junction boxes; of novel current transformer boxes, and of novel cable and transformer junction boxes;
- 60 Another object is concerned with means for mounting certain of the boxes, particularly pot head and certain transformer junction boxes in insulated relation to the structural framework;
- 65 A further object relates to novel connector provisions, such as for use in the transformer boxes and in junction boxes; novel bus connectors for contact caps; novel right angle offset bus connectors; braid bus connectors for use in pot head boxes or cable entrance boxes; parallel bus connectors for transformer boxes; all designed with a view of standardizing and facilitating production, simplifying installation and furnishing high class products of utmost safety and reliability in use;
- 70 Another object is concerned with a novel oil retaining housing which is interposed at certain places in the conductor sheathing with the purpose of retaining the oil therein, preventing leakage, and also preventing the flow of oil from one section to the other when not desired;
- 75

Still another object has to do with a novel alignment joint interposed in the cable sheathing at certain places for simplifying the alignment of the same;

Still another object relates to the provision of novel motor operated means for simultaneously elevating as well as for lowering certain phase equipment, such as oil circuit breakers of three phases, being a departure from the method which necessitates an elevating truck as shown in my aforementioned patent, and permitting the simultaneous lowering or elevating of a plurality of such oil circuit breakers.

I have enumerated the salient objects of my invention, which is shown in the accompanying drawings and particularly described in the detailed description which is yet to follow. It will be understood of course that I have enumerated only the conspicuous objects and features of my invention. There are several other objects which will appear as the description progresses.

Now, in order to acquaint others with my invention and with its aspects and features, I shall describe the invention with reference to the accompanying drawings in which I have shown the several of the above enumerated objects and features and other objects and features as embodied in an actual installation. In the drawings:

Figure 1 represents a plan or top view of the general arrangement of a bay, showing particularly the improved manner of making connection between the junction boxes at bay divisions in accordance with one embodiment, the placing of the conductors and buses within tubing supported between the junction boxes, and connections to the current transformers and oil circuit breakers;

Figure 2 illustrates a side view into the switching arrangement transversely of Figure 1, showing particularly the manner of terminating the cables at the ground level or half way between the framework and ground, and also the connections to the current transformer boxes and oil circuit breakers. The current transformer, it will be noted, is shown in this figure in a plane below the cross conductors;

Figure 3 represents a partial top view similar to Figure 1, showing particularly the manner of making connection to the current transformer;

Figure 4 is a view of a transformer connection illustrating a connection reverse from the one shown in Figure 3;

Figure 5 shows a partial transversal side view with certain parts omitted and broken away, illustrating particularly the connection to the current transformer and to the potential transformer. The current transformer shown in this figure is in the same plane as the cross conductor instead of being below the plane of the cross conductor as is shown in Figure 2. This particular arrangement reduces the dimensions of the difficult transformer box structure;

Figures 6, 6', and 7 are single line diagrams showing the connections for the arrangements shown in Figures 1, 3, and 4, respectively;

Figure 8 illustrates one embodiment of a novel bus coupling shown on a smaller scale in Figures 1 and 3, and also illustrates one embodiment of a novel expandible bus enclosure coupling as employed in the general arrangement shown in Figures 1, 2 and 3 at the bay divisions. Another method and means for making the bus coupling and bus enclosure coupling is also shown in Figures 67 to 69, inclusive;

Figures 8', 9, 10, 11, and 12 are details showing the assembly of the bus coupling and the as-

sembly of the bus enclosure coupling illustrated in Figure 8;

Figure 13 illustrates the manner of insulating the base of a column or pillar from the frame structure in order to provide a fault bus protective system through the frame structure, and also shows the mounting of a transformer on the frame structure for indicating grounds on any bus. The corresponding section will be cut off 10 in such a case.

Figure 14 is a plan or top view of a general arrangement of a metal clad switch gear, showing a sectionalizing and a feeder bay;

Figure 15 is a plan or top view of the general arrangement of metal clad switch gear, showing a generator bay and a reactor bay;

Figures 16 and 17 are side elevations of the general arrangement shown in Figures 14 and 15, illustrating the arrangement of cable entrance and of certain junction boxes;

Figure 18 is a single line diagram showing the circuit connections in the various bays in the general arrangement represented in Figures 14, 15, 16, and 17;

Figure 19 is a side view into the interior of the general arrangement on line 19—19 of Figure 14, viewing the switch gear unit of the sectionalizing bay;

Figure 20 represents a side view into the interior of the general arrangement on line 20—20 of Figure 14, viewing the switch gear unit of the feeder bay;

Figure 21 illustrates a side view into the interior of the general arrangement on line 21—21 of Figure 15, viewing the switch gear unit of the generator bay;

Figure 22 is a side view into the interior of the general arrangement on line 22—22 of Figure 15, viewing the switch gear unit of the reactor bay;

Figure 23 represents a sectional view into the interior of the reactor bay, taken on line 23—23 of Figure 15 and illustrates the arrangement of certain junction boxes and conductors;

Figure 24 shows a partial side view of the framework on line 24—24 of Figure 15, at a bay division;

Figure 25 is a partial front view of the framework on line 25—25 of Figure 15 at the bay division;

Figure 26 illustrates a plan view of the cable entrance boxes on the sectionalizing bay and is taken on line 26—26 of Figure 19;

Figure 27 represents a plan view of the cable entrance boxes on the generator bay and is taken on line 27—27 of Figure 21;

Figure 28 is a plan view of the upper cable entrance boxes on the reactor bay, housing the connections of the cables leading to the reactors, and is taken on line 28—28 in Figure 22, the side view of these cable boxes being shown in Figure 22;

Figure 29 shows a plan view of the lower cable entrance boxes on the reactor bay, housing the connections to the cables from the reactors, as seen on line 29—29 in Figure 22;

Figures 30 and 31 are a front and side view, respectively, of a junction box used in the sectionalizing bay shown in Figures 14 and 19, in which a junction is made between a bus and a conductor leading to a potential transformer;

Figures 32 and 33 represent front and side views, respectively, of a junction box employed 75 in the reactor bay shown in Figures 15 and 22,

in which a junction is made between a bus and a conductor leading to a potential transformer;

Figures 34 and 35 show a front view and a side view, respectively, the side view in section, of a current transformer and junction box used in the sectionalizing bay shown in Figures 14 and 19;

Figures 36 and 37 are a top and a side view, respectively, of a connector employed for making connection in the transformer and junction box illustrated in Figures 34 and 35, and elsewhere;

Figures 38 and 39 represent two views of a T-bus connector employed for making the bus connection in the transformer box shown in Figures 34 and 35 (used in connection with the sectionalizing bay), and in the junction box shown in Figure 48 (used in the generator bay, in the feeder bay and in the reactor bay shown in the Figures 19, 20, 21, and 22, respectively);

Figures 40 and 41 illustrate a sectional side view and a front view, respectively, of an oil retaining housing used at various places in connection with all of the bay units illustrated in the Figures 14 and 15 in plan view and in the Figures 19 to 22, inclusive in side views;

Figures 42 and 43 show a sectional side and a front view, respectively, of an alignment joint employed at various places in all the bay units illustrated in the Figures 14 and 15 in top or plan views, and in Figures 19 to 22, inclusive, in side views;

Figure 44 is a cable entrance or so-called pot head box used in conjunction with the sectionalizing bay unit shown in Figures 14 and 19, and also in the generator bay unit shown in the Figures 15 and 21;

Figure 45 shows a junction and current transformer box similar to the one shown in sectional views in Figures 34 and 35, illustrating particularly the method and means of mounting this box;

Figure 46 is a view taken on line 46—46 of Figure 44, looking in the direction of the arrows, and showing how the upper part of the pot head box is mounted on the structural framework in insulated relation therefrom;

Figure 47 shows the manner and means of mounting the lower portion of the cable entrance or pot head box and is taken on line 47—47 of Figure 44, looking in the direction of the arrows;

Figure 48 represents another embodiment of a junction box, used in connection with the feeder bay shown in Figures 16 and 20, and also in connection with the generator bay shown in Figures 15 and 21;

Figures 49 and 50 are two views of a bus connector for a contact cap of the oil circuit breaker, as used in connection with the generator bay unit shown in Figures 13 and 21 and in connection with the reactor bay unit shown in Figures 15 and 22;

Figures 51 and 52 are two views of another bus connector for a contact cap to the oil circuit breaker in the generator bay Figures 15 and 21. A modification of a bus connector for use in connection with the reactor bay is shown in Figures 70 and 71;

Figures 53 and 54 illustrate two views of a bus connector offset at right angle, as employed in the connection with the generator bay shown in Figures 15 and 21;

Figures 55 and 56 show two views of a braid bus connector used in the pot head box such as shown in Figure 44, which is employed in the gen- 75

erator bay Figures 15 and 21, and also in the reactor bay illustrated in Figures 15 and 22;

Figure 57 is a top view of a pot head connector in the cable entrance or pot head box shown in Figure 44, which is employed in the generator bay illustrated in Figures 15 and 21, and in the reactor bay shown in Figures 15 and 22;

Figure 58 shows the pot head connector as seen on line 58-58 in Figure 57, looking in the direction of the arrows;

Figure 59 is a side view of the pot head connector in right angle to Figure 58, taken in the direction of the arrows 59-59 in Figure 57;

Figure 60 shows a plan or top view of a pot head connector when three outgoing cables are being used;

Figures 61 and 62 are views taken on lines 61-61 and 62-62, respectively, in Figure 60, looking in the direction of the arrows;

Figures 63 and 64 are two views of a parallel bus connector employed in the transformer box in the generator bay unit Figures 15 and 21, and in the reactor bay unit shown in Figures 15 and 22;

Figures 65 and 66 are a plan and a side view, respectively of a bus coupler employed in joining bus sections;

Figure 67 shows a longitudinal section through a bus enclosure coupling between a junction box and a bus pipe and also the bus coupling disposed therein. This coupling shows various improvements over the one shown in the Figures 8 to 12, inclusive;

Figure 68 shows a longitudinal section through a bus enclosure coupling between two bus pipes;

Figure 69 represents a detail of the coupling shown in Figures 67 and 68, on an enlarged scale;

Figures 70 and 71 illustrate a bus connector similar to the one shown in Figures 51 and 52, but specifically designed for use in the reactor bay shown in Figures 15 and 22;

Figure 72 is a top or plan view of novel motor operated provisions individual to the phase equipment of a bay, for simultaneously elevating or lowering three phases of the circuit breakers. The elevating equipment shown in this figure operates by means of a worm gear.

Figure 73 represents a side view of the elevating mechanism shown in Figure 72;

Figure 74 is a partial side view transversally to the equipment as mounted on the structural framework, showing a further view of the novel elevating mechanism;

Figure 75 is a view corresponding to the one shown in Figure 74, but illustrating the elevating equipment in operation, with the oil circuit breaker in disconnect position;

Figure 76 illustrates a view analogous to Figure 75, showing the oil circuit breaker in inspection position;

Figure 77 represents a further view of the elevating equipment in operation, with the oil circuit breaker in removal position; and

Figures 78, 79, and 80 are similar to the views shown in Figures 72, 73, and 74, but illustrate a modified elevating equipment having direct motor drive to worm gears and direct drive from the worm gears to certain shafts instead of belt and bevel gear driving connections shown in the former case.

I will now describe the invention in detail with reference to the above enumerated drawings. I shall not enter into a detailed discussion of parts which may be assumed to be known in the art, but shall limit the discussion to those por-

tions which are either new, include, or show improvements which I consider part of my invention.

Referring now to Figures 1 and 2, it will be remembered that these figures illustrate a plan or top view and a side view of a bay, which may be a generator or feeder bay, in which are incorporated numerous improvements.

The structural framework comprises vertically disposed columns designated in Figure 1 by the numerals 1, 2, 3, and 4. These columns or posts are mounted in insulated relation to the bases 5, 6, 7, and 8. The insulating mounting joints are shown in Figure 2 at 9 and 10. These vertical pillars or posts support longitudinally disposed beams or girders such as the girders 11, 12, 13, 14, 15, and 16. Disposed transversely to the vertical framework, are beams or girders, such as 17 and 18 tying the framework laterally and providing a means for mounting the supporting structure for the junction boxes and the several apparatus in overhead elevated position. The oil circuit breakers, such as designated by numerals 19 and 20 in Figure 2, and the potential transformers such as 21, are also mounted in overhead position.

Between the vertical posts such as 1 and 4 shown in Figure 2, on the floor, are mounted suitably longitudinally extending rails such as 22 and 23. A platform 24 provided with suitable rollers which engage the rails 22 and 23 is thus movable longitudinally through the station comprising several bays such as the one shown. On this platform 24 is mounted an elevating truck 25 which is movable laterally of the switch gear 35 on rollers 26 and 27. This truck has been shown in dotted lines in Figure 2. When it is desired to disconnect a circuit breaker or a potential transformer, the truck 25 will be raised, the corresponding apparatus will be disconnected from the framework and lowered by means of the elevating truck 25, and may then be conveniently transported longitudinally to the switch gear below the transverse girders and the apparatus disposed in overhead position, and thus removed from the switch gear. The insertion of an apparatus or other equipment into the desired overhead position is equally simple and may be accomplished by means of the elevating truck 25. This elevating truck is particularly described in my copending application previously mentioned which may be consulted for details not mentioned in this specification.

The above described elevating truck is common to several bays. Three phases of oil circuit breakers can be removed or inserted at a time. I have also disclosed, in the present case, a novel screw operated elevating mechanism which ties three phases of oil circuit breakers together and is individual to a bay. I shall describe this mechanism later on in detail.

On the transversely extending girders such as 17 and 18 are mounted the supports for the junction boxes which are provided for making connections between the various apparatus and the bus conductors. The tubular sheathing enclosing the bus conductors extends between the junction boxes and is supported thereby. The transformer enclosing boxes and the oil reservoirs are likewise mounted on the overhead supports.

The phase conductors are designated in Figure 75

- 2 by the numerals 28, 29, and 30 which represent the main bus, and 31, 32, and 33 representing the reserve bus. These buses are of standard length sections and are enclosed in standard length tubing which is self-supporting between the junction boxes on the structural framework. Special provisions are made at the bay divisions for joining the buses and also the tubular enclosing pipes for the buses. These special provisions for joining the bus sections and the pipe sections at the bay division are shown particularly in Figures 8 to 12, inclusive, and will be described in detail later on. With reference to Figure 1, these bus enclosure couplings containing the bus couplings, are designated by the numerals 34 to 41, inclusive. Intermediate of these bus enclosure couplings at the bay divisions and the junction boxes are standard length tubing such, for example, as designated by numerals 42 and 43, in Figure 1, showing how the coupling 35 is connected to the junction box 44 and how the junction box 44 is connected by means of the intermediate tubing 43 to the bus enclosure coupling 39 at the bay division. The bus 30 extends through the bus enclosure coupling 35, through the intermediate tubing 42, and through the intermediate tubing 43 with a branch connection provided at 45 for connecting the bus 30 to a contact cap of the oil circuit breaker located below the junction box 44.
- 30 As is shown in Figure 2, the cables 46, 47 and 48 enter underground through a suitable conduit and terminate in the so-called pot head or cable entrance box 49 mounted on a console 50 which is attached to suitable longitudinally extending cross bars mounted on the vertical posts, such as 1. The necessary connections are made within the pot head box such as 49 and the conductors are then disposed within suitable tubing such as 51 which is connected and terminates in the box 52. The latter may be mounted on a suitable console 53 attached to the longitudinally extending beam or girder such as 11 or 12. The cross conductors extending from the various junction boxes such as 52, shown in Figure 2, and 52, 52', 52" in Figure 1, are disposed within tubing such as 53', 54, 55 attached at one side to the corresponding transformer housing such as 56 located in the middle of the framework in overhead position. Disposed within the transformer box are the transformers such as 57. The cross conductors such as 58 extend between the contact caps such as 65 and 66 housed in junction boxes such as 59 and 60. It will be seen that a connection is made at point 61, from the cross conductor 58 to the transformer 57 and from the latter by means of a connector 64 to conductor 62 leading to junction box 52 and disposed within the tubing 53'. The connection from cross conductor 62 to the transformer 57 is indicated at 64.
- 60 It will be observed that the current transformer 57 as shown in Figure 2, is in a plane below the cross conductor 58 connecting the contact caps 65 and 66 which connect to the respective switching contacts of the oil circuit breakers 19 and 20. The arrangement as shown in Figures 1 and 2 makes it possible to make connections to the current transformer from either side, adapting the unit to be used in a system either as a generator or as a feeder bay.
- 70 The single line diagram represented in Figure 7 shows the connections for the arrangement discussed above. Most of the numerals in this figure appear also in Figures 1 and 2, designating like parts. The main bus may correspond to the bus 30 shown in Figure 1. A branch conductor

connects the main bus 30 within the junction box such as 44 to the switching point 67 by way of a suitable contact cap of the oil circuit breaker such as 19. The other pole of the oil circuit breaker is connected through the switching point 68 (which connects to a suitable contact cap such as 65 in Figure 2) to the cross conductor 58 connecting to the switching point 66' by way of the contact cap 66 (Figure 2) within the junction box such as 60 of Figure 1. The other pole of the oil circuit breaker 20 (in Figure 7) is connected by means of a switching point 70 to the reserve bus 31 which is disposed within the tubings 36' and 33 connected to the bus enclosure couplings 36 and 40, respectively, as shown in Figure 1. 15 Branching from the cross conductor 58 (in Figure 7) is a connector 61, corresponding to the connector 61 in Figures 1 and 2, leading to the current transformer 57 which is connected at the other side by means of a conductor 64 to the conductor 62 leading over the switching points 71 and 72 to the fuse 73 (also shown in Figure 1) and over the switching point 74 to the resistor 75 which is connected to the potential transformer 21. The other side of the conductor 62 25 may be connected to the generator 76 and to the auxiliary transformer 77 over a switch 78. The auxiliary transformer may be used for fans and the like.

Referring again to Figure 1, oil reservoirs such as 79 and 80 may be suitably provided on the framework and connected by means of piping 81, 82 and 83, and 81', 82', 83' to the various junction boxes, such as the junction boxes 59 and 60 which are supplied with oil by the piping 83 and 83', respectively. The prominently shaded points shown in the piping 81, 82, 83 and 81', 82', 83', leading from the oil reservoirs 79 and 80 indicate insulating joints. I have described the arrangement of the oil reservoirs in my copending application above referred to in detail which may be consulted for any particulars not mentioned herein in connection with the general arrangement shown in Figure 1.

The hooks designated in Figure 2 by the reference numerals 1'-2' and 3'-4' are provided for holding the oil circuit breakers 19 and 20 in disconnect position.

Referring now to the Figures 3, 4, and 5, these figures show an arrangement in the transformer 50 housing which is slightly different from the one discussed in connection with Figures 1 and 2. It will be remembered that the transformer in the arrangement shown in Figures 1 and 2, as is particularly seen in Figure 2, is located below the plane of the cross conductor 58 which connects the oil circuit breakers such as 19 and 20. In the arrangement shown in Figures 3, 4, and 5, I have shown a modification in which the current transformer lies in the same plane with the cross conductor. This is an improvement of particular virtue. It permits the same interchangeability from either side of the structure to the current transformer, and reduces the dimensions of the current transformer housing which is quite a difficult structure in the arrangement. The same reference numerals as used in Figures 1 and 2, some of them primed for convenience sake, indicate like parts in Figures 3, 4, and 5.

The cable terminates underground in the cable entrance or pot head box 49 and the current conductor 62 is connected through a tubing 53 within a junction box 52 as previously described. The circuit breakers 19 and 20 are suspended in overhead position on the framework part of which

- and 158 are drawn through the registering openings in the flange members 165-166, in the supporting plates 146-147 and in the insulating plate 148 to provide proper insulation for the bolts 151 and 152. Suitable insulating washers may be attached at each end, separating the heads of the bolts 151 and 152 and the nuts 153 and 154 in insulated relation from the member 144 and flanges 165 and 166 of the pillar 145. The insulating members are shown prominently shaded. The nuts 153 and 154 are drawn on the threaded portions of the bolts 151 and 152 holding the pillar or post 145 firmly attached to the supporting member 144 which is firmly attached to the column base 142.

It will be seen that the mounting of the post 145 on the column base 142 as discussed above insulates the same effectively from the column base. It is of course understood that all the pillars and posts supporting the overhead structure are similarly attached in insulated relation from their respective column bases.

The current transformer 159 may be attached to suitable supports such as the cantilever bars 162 and 163. Secondary leads such as 160 may be provided for connecting the current transformer to suitable equipment. Ground connection for the transformer is provided at 161 and a connection to the framework is provided at 164. The manner of insulating the supporting pillars of the elevated structural framework from the column bases as above described provides a simple fault bus protective system. The sheathing for the bus conductors is sectionally grounded to the framework as was previously mentioned. Circulating sheath currents are, therefore, sectionally separated and undesired heating of the sheathings is prevented. Now, should a fault develop in a bus section due to ground potential on the bus, a circuit will be closed through the corresponding transformer, such as the one shown at 159 in Figure 13, and the faulty bus section will be cut off.

In Figures 14 and 15 is shown the plan or top view of the general arrangement comprising a sectionalizing bay, a feeder bay, a generator bay, and a reactor bay. The Figures 16 and 17 are longitudinal side views of the general arrangement shown in Figures 14 and 15 with non-essential details omitted for the sake of clarity. In the Figures 19, 20, 21, and 22, I have shown cross sectional views transversely through the switching arrangement shown in Figures 14 and 15 taken on the lines 19-19, 20-20, 21-21, and 22-22, respectively. In Figure 18 is shown a single line diagram illustrating the principal circuit connections in the various bays.

The general arrangement shown particularly in Figures 14 to 18, inclusive, represents a complete bus and switch station. Numerous improvements are incorporated therein, in addition to the various improvements already discussed in the foregoing, which will be explained presently in detail. For convenience' sake, I shall first describe the physical structure of the general arrangement shown in Figures 14 to 17, inclusive.

Referring particularly to the Figures 16 and 17, it will be seen that the structural framework for supporting the equipment in overhead position comprises again vertically disposed pillars or columns such as 165, 166, 167, 168, 169, and 170. It will be understood, of course, that each of these pillars is insulated from its corresponding column base as was described above. Longi-

tudinally extending beams of structural steel, such as 171, 172, 173, and 174 are supported by the vertically disposed pillars or columns. The Figures 16 and 17 show but one side of the general arrangement; it will be understood that there is a companion pillar for each pillar shown, and likewise companion beams on the other side of the structure.

As will be seen from an inspection of Figures 14 and 15, on the other side of the general structure, supported longitudinally on the vertical columns are beams such as 175, 176, 177, and 178. Cross beams such as 179, 180-181, 182-183, 184-185, and 186 are supported on the vertical columns, limiting the respective bay divisions. The cross beams 179-180, for example, limit the extent of the sectionalizing bay; the cross beams 181-182 define the longitudinal limits of the feeder bay within the general arrangement; the cross beams 183-184 limit the extent of the generator bay longitudinally of the general arrangement; and the cross beams 185-186 define the longitudinal limits of the reactor bay. Other longitudinal and transverse cross beams are supported on this general structural framework, carrying, in overhead position, the various apparatus and equipment within each bay.

I shall first describe the details of the sectionalizing bay which is shown in plan view in Figure 14, defined by the cross beams 179 and 180, and in the view of Figure 16 disposed between the pillars 165 and 166. A transverse sectional view into the interior of the general arrangement of the sectionalizing bay is shown in Figure 19 which is taken on line 19-19 of Figure 14. I will describe the improvements incorporated in the sectionalizing bay with reference to the above mentioned figures, and then improvements which I have incorporated in the other bays.

Referring now specifically to the sectionalizing bay as defined above, and shown in Figures 14, 16, and 19, it will be seen that the cable entrance or pot head boxes 187, 188 and 189, in Figure 16, are supported on the framework between the columns 165 and 166 on structural beams such as 190 and 191. The specific construction of such a cable entrance box or pot head box used in connection with the sectionalizing bay under discussion is shown in Figure 44. This figure, showing a novel pot head or entrance box employed in the sectionalizing bay, will therefore be described next in detail.

Referring now to Figure 44, it will be seen that the cable entrance or pot head box comprises, substantially, a body structure designated by numeral 192 which is provided with a flange 193 for receiving a cover such as 194. At the lower side of the cable box 192 are the pot head sleeves such as 195 for receiving the cable sheath such as 196. On the upper side of the box are flange connections such as 197 for attaching the standard length tubing such as 198, 210, and 211 (Figure 16) to the pot head box. It will be seen from an inspection of the Figures 44, 46, and 47, that the pot head box is provided with ears 198' and 199 for attachment to the cross bars or girders such as 190 and 191 which are mounted between the vertically disposed pillars 165 and 166 (Figure 16). The box is also provided with ears such as 200 and 201 for attachment to the lower cross beam or girder 191. The attachment of the cable entrance box or pot head box is, as is shown in Figures 44 to 47 by means of insulating material which is 75

interposed between the box and the supporting beam. Specifically, the cable entrance box 192 rests at its lower end on the insulating strip 202 which, in turn rests on the beam 181. The attachment is by means of bolts such as 203 and 204 and corresponding nuts. The bolts 203 and 204 are also insulated from the body of the cable entrance box 192 by means of insulating washers such as 205 and 206. The upper part of cable entrance box 192 is insulated from the corresponding supporting beam in a similar manner by means of insulating strips such as 207 and 208. The bolts holding the ears 198 and 199 of the upper part of the cable entrance box to the supporting girder 190 are also insulated from the box by means of suitable insulating washers such as the one shown at 209 in Figure 44. The cover 194 of the pot head box 192 is of course removable and may be attached by means of suitable bolts. 20 When attached, it closes the box oil tight.

Attached to the pot head boxes 187, 188 and 189 shown in Figure 16 and described in detail with reference to Figures 44, 46, and 47, are the standard length tubings 198, 210, and 211. These 25 are ordinary tubings for sheathing the conductors enclosed therein.

As is shown in Figures 16 and 19, the sheathings 198, 210 and 211 are not directly connected to the current transformer boxes 215, 216, and 217, but 30 a link is provided in each instance, represented in the alignment joints such as 212, 213, 214 and 214'. The structure of such an alignment joint is particularly shown in the Figures 42 and 43 which will be described next.

35 Referring now to the Figures 42 and 43, it will be seen that such an alignment joint as the one illustrated in Figures 16 and 19 and designated there by the reference numerals 212, 213, 214, and 214', comprises a thin metal casing 218 which is capable of expansion and contraction. The circular ends of this casing are laterally bent to form flanges such as 219 and 220. Ring-like members 221 and 222 are attached to the flanges 219 and 220, respectively, thereby providing a rigid flange 40 which is used for joining to the alignment joint the tubing such as 198, 210 and 211 shown in Figure 16, and for also joining to the alignment joint the attachment to the current transformer junction boxes such as 215, 216, and 217 in Figure 16. The flanges of the alignment joints are for this purpose provided with holes or openings such as 223 to 230, inclusive, as particularly shown in Figure 43. The cables rising within the tubing 198, 210, and 211 in Figure 16 are provided 55 with an insulation indicated in Figures 42 and 43 by reference numeral 231.

60 The purpose of this alignment joint interposed between the vertically rising tubing and the current transformer junction boxes is to allow for the convenient alignment of the tubing when the same is connected to the transformer boxes. The metal casing 218 of the alignment joint may be of copper, thin walled and adapted to permit a certain displacement, at the same time providing a good and reliable casing for the cable.

65 Again referring to the Figures 16 and 19, the attachment of the alignment joints such as 212, 213, 214, and 214' to the corresponding current transformer junction boxes such as 215, 216, and 217 is made by means of the flanges on the respective alignment joints and by corresponding flanges on the short entrance tubing on the current transformer boxes, each of which is suitably 70 flanged so that it can be connected to the flange

of the corresponding alignment joint by means of bolts and nuts.

The structure of the current transformer boxes 215, 216 and 217 used in connection with the sectionalizing bay shown in Figures 14, 16, and 19, 5 will be described next.

This current transformer box is particularly shown in Figures 34 and 35. Figure 34 represents a front view of the box with the cover 232 removed. Figure 35, it will be seen, represents a 10 side view with the housing 233 in cross section to illustrate the interior of the current transformer box.

15 It will be seen that the box consists of an enclosure 233 provided with a flange 234 to which 15 may be attached the flanged cover 232 by means of suitable bolts and nuts. The cover 232 is attached to the box 233 in oil tight relation thereto, by interposing a gasket such as 235 between the flange 234 of the box 233 and the flange of the 20 cover 232. This is particularly illustrated in Figure 35. At the lower end of the current transformer box is shown an entrance tubing connection 236 which is flanged for attachment to the alignment joint such as 212, 213, and 214, 25 shown in the Figures 16 and 19. On the upper part of the box 233 and in the rear thereof is provided a short tubing connection 237 which is suitably flanged for making connection with a similarly flanged oil retaining housing to be described later on.

25 Mounted in the interior of the current transformer box shown in Figures 34 and 35 is the current transformer designated by numeral 238. The attachment of the terminals of the current 30 transformer to the respective conductors at the entrance of the current transformer box and at its exit, are made by connectors 239 and 240.

The connector shown at 239 in Figures 34 and 35, is particularly shown in detail in the Figures 36 and 37.

35 Referring now to these Figures 36 and 37, it will be seen that the connector consists of two clamp-like portions 241 and 242, each having ears such as 243—244, 245—246, the ears on the clamp 40 portion 241 corresponding to the ears 243—244 on the clamp portion 242 being designated by numerals 247 and 248. The four ears of each of the clamp portions 241 and 242 register and bolts such as 249, 250, 251, and 252 are drawn through 50 holes in the ears of the clamp portions and fastened by corresponding nuts such as 253, 254, 255, and 256. Numeral 242' indicates a potential transformer connection.

45 Referring now again to the current transformer 55 box shown in Figures 34 and 35, it will be seen that the connector 239 which was just described in detail with reference to Figures 36 and 37, connects the lower terminal of the current transformer 238 with the bus conductor rising through 60 the entrance tubing such as 236 of the transformer box.

The connection of the upper terminal of the current transformer 238 with the corresponding bus leaving the current transformer box through 65 the exit tubing 237 shown in Figures 34 and 35 is made by means of a T bus connector 240 which is particularly shown in Figures 38 and 39. These figures will therefore be described next.

70 Referring now to Figures 38 and 39, it will be seen that the T bus connector consists of two clamp portions designated by reference numerals 257 and 258. One-half of the clamp portion is adapted to surround the upper terminal of the current transformer which is designated in the 75

is shown, namely, the cross beam 17 connecting to the vertically disposed posts 1 and 4 which are supported on the base member 5 and 8, respectively. The junction boxes 44 and 61 are supported on the framework in overhead position as in the former case and enclose the switching contacts for the oil circuit breakers 19 and 20 as well as part of the cross conductor between the oil circuit breakers, which is designated by numeral 58.

The difference between the arrangement in Figures 3 and 5 and the one previously described resides, as has been mentioned, merely in the fact that the current transformer lies in the same plane with the cross conductor 58 which connects to the switching contacts of the oil circuit breakers 19 and 20. The connection between the cross conductor 58 and the current transformer 57 is shown in Figure 3 at 84. The other side of the current transformer 57 is connected to the current conductor 62 which leads through the current transformer box 56 and enters the tube 53. A connection 85 branches off from the conductor 62 to the contact cap of the potential transformer 21.

In Figure 4 is shown the connection between the cross conductor, the current transformer and the potential transformer as made from the other side of the current transformer. The reference numerals applied in Figure 4 are primed and refer to like parts in Figures 3 and 5.

The circuit diagram shown in Figure 6 corresponds in its details to the circuit diagram shown in Figure 7 but it illustrates specifically the different connections shown in Figures 3 and 5. It will be seen that the main bus 30 is again connected by means of a suitable connector to a switching point 67 which is enclosed in the junction box 44 and connects to the oil circuit breaker 19. The other pole of the oil circuit breaker is connected to a switching point 68 within the junction box 44 and then to the conductor 58 connecting to the switching point 66' of the reserve oil circuit breaker 20. The other pole of the oil circuit breaker 20 is connected to the switching point 70. The switching points 66' and 70, it will be remembered, are within a junction box such as 61 in Figures 3 and 5. The latter switching point 70 is then connected by means of a suitable conductor to the reserve bus 31. The conductor 84, also shown in Figure 3, branches off from the cross conductor 58 and leads to the current transformer 57. The other side of the current transformer 57 is connected to the conductor 62 which is disposed within the tubing 53 in Figures 3 and 5. Connector 85 branches off from the conductor 62, leading to switching points 71 and 72, then to a fuse 73, to a switching point 74, and over a resistance 75 to the potential transformer 21. Connected to the conductor 62 may be the generator 76 and, over a switch 78 the auxiliary transformer 77 provided for fans and the like, as is also shown in Figure 7.

The circuit diagram shown in Figure 6' illustrates particularly the circuit connections of the structure shown in Figure 4. It will be seen that the conductor 84' shown in Figure 4 as branching off from the cross conductor 58' is connected to one side of the current transformer 57', the other side being connected to the conductor 62'. The connector 85' shown in Figure 4, is shown in Figure 6' to connect to the potential transformer 21' over the various switching points, a fuse, and a resistor, as already discussed in connection with the circuit diagram shown in Fig-

ure 6. This interchangeability makes it possible to employ the corresponding unit either as a feeder bay or as a generator bay, if desired.

It will be understood that suitable covers are provided for the various junction boxes shown in Figures 1, 2, 3, and 5, the covers being designated in Figure 2 by the reference numerals 88 to 92, inclusive. Suitable diagonally attached covers are provided for the cable entrance or pot head boxes such as 49 and for the junction boxes such as 52 in which the vertically rising conductors are connected horizontally across the switch gear, and disposed in suitable tubing as described previously.

Summarizing the salient features disclosed so far with reference to the drawings, Figures 1, 2, 3, 4, 5, 6, 6', and 7, discussed above, it will be seen that I have provided a novel method and novel means for removing the cables at the current transformer boxes. The improved scheme shows the possibility of connecting conductors from either side of the current transformers depending on the function of the unit as a feeder bay or as a generator bay. In one modification, the current transformer is disposed below the plane of the cross conductor within the current transformer box, while in the other modification, as particularly shown in Figures 3 to 5, inclusive, the current transformer is disposed in the same plane as the cross conductor. As a further salient point, I desire to mention the method of terminating the cables at the ground level or at a point between the ground and the structural framework as is particularly shown in Figure 2. The cable entrance or pot head boxes, such as 49, may, of course, be disposed at any level on the structural framework. It is also feasible to put the cable entrance boxes at the ground level and to extend the vertical tubing for the rising conductors and connecting the cable entrance boxes with the junction boxes.

I shall now continue the description with reference to Figures 8 to 12, inclusive, which show a novel and improved manner of joining the bus sections and the tubing for enclosing the bus conductors, at the bay divisions. It may be mentioned at this point that I have made further improvements over this bus enclosure coupling and bus coupling as shown in Figures 8 to 12, inclusive, which is particularly shown in the Figures 67, 68, and 69. The latter figures, however, will be described in connection with the general arrangement of switch gears, shown in other figures, in which they are used. At this point of the description, I shall describe the bus coupling and the bus enclosure coupling at the bay divisions which are used in conjunction with the general arrangement of the switch gear as disclosed in Figures 1, 2, and 3.

Referring now to the Figures 8 to 12, inclusive, it will be seen that the insulation of each of the bus sections 100 and 101 is suitably removed at 124 and 127. An intermediate bus section 102 is provided with the insulation cut off at each end as shown at 125 and 126. These bus sections 100 and 101 are joined or coupled at the bay divisions by means of the intermediate coupling 102, by lining up the blank ends 124, 125 and 126, 127. Tubular sectional clamps 103 and 104 are drawn over the blank ends of the bus sections 100-101 and of the intermediate section 102, as is particularly shown in Figure 8, and these clamps are drawn together by suitable bolts, firmly joining to the bus sections 100 and 101. Suitable wrapping 105 and 106 is pro-

vided at the point where the blank portions of the bus sections and of the intermediate bus section are joined.

The above operation is carried out with the 5 tubing 107 and 108 enclosing the bus sections 100 and 101 in place as shown particularly in the arrangement, Figures 8' to 12, inclusive, which show the position of the tubing and of the bus enclosure coupling members in position when the 10 bus sections are joined as above described.

Attached to the intermediate bus section 102 is 15 the insulating disc 120, the attachment being made prior to joining the intermediate bus section 102 with the bus sections 100 and 101, by means of suitable packings 130 and 131, and members 128 and 129 holding the packings and insulating disc 120 on the intermediate bus sections 102.

The bus enclosure coupling, that is to say the coupling of the tubing 107 and 108, comprises 20 several parts which are slidably mounted on the tubing 107 and 108, respectively. The pipe coupling comprises, specifically, two flanged members 109 and 110. The flanges on these members are shown at 123 and 123'. The member 109 is 25 slidable on the tubing 107 and attached to the mounting ring 113 as particularly shown in Figure 8'. A companion mounting ring 112 is also slidable on the tubing 107 and packing washers 118 and 119 are provided intermediate of the 30 mounting rings 112 and 113. The tube coupling member 110 is attached to the expandable bellows 111 as particularly shown in Figure 12, and the latter is attached to a mounting ring 132 in a similar manner as the tube coupling member 109 35 is attached to the mounting ring 113. A companion mounting ring 133 for the mounting ring 132 is provided slidable on the tubing 108 and disposed between the rings 132 and 133 are the packing washers 118' and 119' corresponding to the washers 118 and 119 used in conjunction with the tubing coupling shown in Figure 8'.

The above mentioned members of the bus 40 enclosure coupling are positioned on the tubing sections 107 and 108, being slidable thereon, as is shown in the arrangement of Figures 8' to 12, inclusive. While these coupling members are in the position as shown, the bus sections 100 and 101 are joined by means of the intermediate bus section 102 as was described previously. It will 45 be remembered that the intermediate bus section 102 carries, permanently attached to it, the insulating disc 120. Now, when the bus sections 100 and 101 are joined and provided with wrapping 105 and 106 as shown in Figure 8, the 50 bus enclosure coupling members 109 and 110 are drawn together and attached to the insulating disc 120 by means of the flanges 123 and 123', respectively.

Coupling rings 121 and 122 provided with suitable holes which register with suitable holes in the flanges 123 and 123' of the members 109 and 110, are attached as shown, and suitable bolts 138 and 139 are drawn through the holes in the ring 122, the flanges 123 and 123' and the ring 60 121 and fastened by means of nuts such as 140 and 141.

The coupling members 109 and 110 are now in a position as shown in the drawing Figure 8, joined together but insulated from each other by 65 means of the insulating disc 120 which is attached to the intermediate bus sections 102.

The rear section of the bus coupling member 109 which is slidable on the tubing 107 is oil tight attached thereto by means of the mounting rings 70 112 and 113 which are drawn together by means

of the bolts such as 114 and 115 and nuts such as 116 and 117. The packing washers 118 and 119 which are interposed between the mounting rings 112 and 113 prevent leakage of oil through the bus coupling. The other section of the coupling, member 110, is attached by means of the 75 mounting rings 132, 133 which are held together by means of the bolts such as 134 and 135 and nuts 136 and 137, preventing the leakage of oil at this point due to the packing washers 118' 10 and 119'.

The bus coupling and the bus enclosure coupling at the bay division is now completed. It will be seen that this novel bus enclosure coupling presents a variety of novel features and improvements. In the first place, it simplifies the assembling of the bus sections. The same may be easily assembled and joined by means of the intermediate bus section 102 by simply sliding the members 109 and 110 off the bus enclosure 20 coupling and the corresponding pipe sections 107 and 108. This feature facilitates the installation and provides ready access to the bus coupling at any time. The pipe sections 107 and 108 are joined securely and in insulated relation from 25 each other due to the insulating ring or disc 120 which is attached to the intermediate bus section 102. Leakage of oil from the sectionalized tubing which encloses the bus section is prevented by means of the packing provided at each 30 end between the mounting rings 112—113, and 132—133, respectively. Oil is also prevented from communicating from one bus section to the other due to the packing 130 and 131 attached to the insulating disc 120 which separates the pipe 35 sections electrically. Oil is fed to the bus sections from the oil reservoirs as was explained previously with reference to the Figures 1 and 2. Another feature of improvement is represented in the expandable member 111 which permits 40 expansion and contraction of the bus enclosing pipe at the bay division.

As mentioned previously, I have disclosed in the present case a further method and means for coupling the bus sections and the bus enclosures 45 at the bay divisions. This other embodiment distinguishes over the one just explained in several respects. It is incorporated in a switch gear yet to be described, and I shall therefore furnish a detailed account of this other embodiment of a 50 bus and bus enclosure coupling later, after showing details of the other switch gear.

Referring now particularly to Figure 13, this figure shows the manner of insulating the column base from the frame structure, and also the 55 mounting of a current transformer on the framework on or between adjacent supporting posts. The column base 142 is provided with two shaft bolts 155 and 156 projecting to the outside. Attached to the column base 142 is a member 144 resting on a supporting plate 143, the attachment being made by means of nuts 157 and 158 engaging the projecting threaded parts of the bolts 155 and 156.

The vertically disposed supporting post or 60 pillar 145 is attached to the member 144 mounted on the column base 142 as follows: A plate 147 is arranged on the member 144. An insulating member 148 is put on the plate 147 and another supporting plate 146 is disposed on top of the 65 insulating plate 148. The pillar 145 is provided with flange members 165 and 166 provided with holes which register with corresponding holes in the supporting plates 146 and 147 and in the insulating plate 148. Insulating bushings 149 70

Figures 38 and 39 by the numeral 259. The upper portions of the members 257 and 258, when joined as shown in Figures 34—35 and 38—39, are adapted to embrace the bus conductor 260 which extends in a right angle to the terminal 259 of the current transformer. Each of the members 257 and 258 is provided with six holes which register when these members are put on the respective current transformer terminal 259 and the end of the bus conductor 260. Bolts such as 261, 262, 263, 264, 265, and 266 are drawn through the registering holes on the members 257 and 258 and fastened thereon by means of corresponding nuts such as 267, 268, and 269 shown particularly in Figure 39.

The T bus connector, above described, is not only used in the transformer box shown in the Figures 34 and 35, but at various places throughout the station, as will be brought out as the description progresses. The manner of mounting the transformer boxes such as the one shown in Figures 34 and 35, which is employed in the sectionalizing bay shown in Figures 14, 16, and 19 and designated in these figures by numerals 215, 216, 217 and 215', 216', 217', is particularly shown in Figure 45 which illustrates the structure of a junction and current transformer box similar to the one discussed in connection with Figures 34 and 35.

It will be seen from Figure 45 that the current transformer and junction box shown in this figure consists of a body 270, provided with a flange 271 for receiving the cover 273 which is provided with flange 272 for registering with the flange 271. The cover 273 may be attached, as was mentioned previously, by means of suitable bolts and nuts. It is of course understood that this cover of the box 270 as well as the cover of the box shown in Figures 34 and 35 is attached so as to provide an oil tight joint between the corresponding flanges. At the lower end of the box shown in Figure 45 may be provided short flanged entrance tubings such as 274, and at the upper part of the box 270 and in the rear wall thereof is provided a short exit tubing 275 also provided with a flange for attachment to a bus enclosing tubing as will be described later on.

Although the boxes shown in Figure 45 and Figures 34 and 35, respectively, may differ in dimensions, their exterior is essentially the same. Integral with the rear wall of the box shown in Figure 45 is a bracket member 276 for attaching the box to a support on the structural framework. As is shown in Figure 45, the attachment to the support 277 is by means of ordinary bolts such as 278 and nuts such as 279. Interposed between the brackets 276 and the support 277 is an insulating strip 280 and an insulating washer 281 is interposed between the head of each bolt such as the bolt 278 which fastens the bracket to the support 277.

Referring now again to Figures 14, 16, and 19, and particularly to the attachment of the current transformer boxes 215, 216, 217, and 215', 216', 217', it will be seen, by inspecting the Figure 19, that the attachment of the current transformer boxes 217 and 216' to the supports 282 and 282' is substantially as described in connection with the Figure 45, and it will also be understood that the current transformer box shown in the Figures 34 and 35 is provided with a supporting bracket similar to the one discussed in connection with the description of the junction and current transformer box in Figure 45.

It will be understood that the structure of the

current transformer boxes 215', 216', and 217' shown in Figures 14 and 19 is the same as discussed above with particular reference to the current transformer boxes 215, 216, and 217. The alignment joint 214', the vertically disposed tubing 211', and the cable entrance or pot head box 189', shown on the right side of Figure 19, correspond in all details to the alignment joint 214, the tubing 211, and the pot head box 189 shown on the left side of Figure 19.

Having now described the cable entrance or pot head boxes, certain alignment joints, and the current transformer boxes used in conjunction with the sectionalizing bay shown in Figures 14, 16, and 19, it will be well to summarize the features and improvements which I have incorporated in this sectionalizing bay as far as described, which I desire to emphasize as features of novelty.

Each of the cable entrance or pot head boxes 20 is a unitary structure provided with mounting brackets for attaching the same to the supporting structure on the framework. The attachment of the boxes to the structural framework is in insulated relation from the latter. The box 25 is provided with short entrance and exit tubing each having a flange for attaching the cables as well as the tubing which encloses the conductors leading to the current transformer boxes. Interposed between the vertically extending tubing 30 and each current transformer box is an alignment joint which permits easy and efficient alignment of the tubing when the same is attached to the current transformer box. The tubing and the alignment joints may be made self-supporting 35 between the cable entrance boxes and the current transformer boxes, respectively. If desired, bracing may be provided for giving additional support to the tubings. Each of the current transformer boxes is provided with short 40 flanged tubing for the attachment of the alignment joints at one side and of certain flanged equipment on the other side. The current transformer boxes are attached to the structural framework in insulated relation therefrom similar 45 to the attachment of the cable entrance or pot head boxes. The equipment disposed within the cable entrance or pot head boxes and within the current transformer boxes is readily accessible due to the removable covers attached to 50 these boxes. The attachment of the covers is so as to provide an oil tight joint. Within the current transformer box are used novel connectors for attaching the terminals of the current transformer to the rising cable conductor 55 and to the bus conductor, respectively. Each of the connectors comprises two companion clamp members joined by means of ordinary bolts and nuts. One of the connectors used in the current transformer box is provided for joining two conductors disposed in a right angle to each other.

A top view taken on line 26—26 in Figure 19 is shown in Figure 26, to illustrate the attachment of the cable entrance or pot head boxes, such as 187, 188, 189 shown in Figure 16, more 65 particularly in their relation to the vertically extending pillars 165 and 166 which define the limit of the sectionalizing bay longitudinally to the general arrangement as shown in Figures 14 to 17, inclusive. It will be seen from Figure 26 70 that each of the boxes is insulated from the cross supporting beam 190, and is of course likewise insulated from the cross supporting beam 191 disposed in this Figure 26 below the cross support 190. It is believed that a more detailed 75

description of Figure 26 is unnecessary in view of the detailed description of drawings explained previously in connection with the attachment of the pot head boxes.

- 5 Continuing the detailed description of the sectionalizing bay with reference particularly to Figures 14 and 19, it will be seen that each of the short flanged exit tubings leaving the various current transformer boxes 215, 216, and 217, 10 and 215', 216', and 217', joins a flanged oil retaining housing designated by the numerals 283, 284, and 285, and on the other side of the equipment the oil retaining housings 283', 284', and 285'. The structure of such an oil retaining 15 housing is particularly shown in Figures 40 and 41 which will be described next.

It will be seen from Figures 40 and 41, that the oil retaining housing consists of a casing 286 provided with flanges 287 and 288. Disposed 20 within this casing 286 are rings of cork or other insulating material 289 and 290 supporting a cylindrical insulator 291. The cylindrical insulator 291 is necessary to insulate the bus from the housing effectively, since the cork spacers 25 289 and 290 which center the bus are not considered to constitute a perfect insulation. Attached to the casing 286 is also a two-way valve 292 provided with operating wheels or cranks 293 and 294, respectively, for admitting oil either 30 through the opening 295 or the opening 296 to either side of the oil retaining housing. The flanged connection 297 on the valve housing 292 is provided for a suitable oil connection. The flanged portions 287 and 288 on the casing 286 35 are provided with circularly disposed holes 298 to 305, inclusive, for attaching the oil retaining housing to the exit tubing on the current transformer box as shown in Figures 14 and 19, and also for attaching the housing to the bus tubing 40 which houses the cross conductors, such as the tubings 306—306' in Figure 19. Each, the exit tubing on the current transformer box as well as the bus tubing being provided with flanges corresponding to the flanges 287 and 288 on the oil 45 retaining housing. The attachment of the flanges is by means of ordinary bolts and nuts. Suitable packing or gasket provisions may be used for making the joints oil tight. This packing will be disposed within the recessed portions 50 287—288' shown in Figure 40.

Now, when it is desired to admit oil into the current transformer box, the valve wheel 293 in Figure 40 will be operated and oil will flow 55 through the opening 295 to the left side of the oil retaining housing and into the current transformer box and related equipment. The valve wheel 294 is operated when it is desired to admit oil into the bus enclosing tubing and related equipment. The valves operated by the wheels 60 293 and 294 may remain open, providing a communication between the bus enclosures such as 306 and the current transformer box such as 217 in Figure 19. However, when it is desired to isolate the current transformer box or the bus 65 enclosing tubing from each other, this may be done by means of the valve provision on the oil retaining housing as discussed, and the oil retaining housing will take care of retaining the oil in that section of the equipment in which its 70 retention is desired. It will be understood, of course, that all the oil retaining housings shown in Figure 14 and designated by the numerals 283—283', 284—284', 285—285', are constructed as discussed in connection with Figures 40 and 75 41 and function in the same manner. The va-

rious bus conductors passing through the oil retaining housings are provided with suitable moulded insulation as is indicated in Figures 40 and 41 by the reference numeral 301.

Referring again to Figures 14 and 19, it will be seen, particularly from Figure 14, that the various bus enclosing tubings designated by numerals 306—306', 308—308', 309—309', extend between the various oil retaining housings 283—283', 284—284', 285—285' and the junction 10 boxes 310—310', 311—311', and 312—312'. The attachment of the bus enclosing tubing and the junction boxes is by means of flanged connections as is plainly indicated in Figures 14 and 19. Each of these junction boxes is connected, by 15 means of a flanged connection, to junction boxes disposed on the structural framework above the various oil circuit breakers as is indicated particularly in Figure 19, which shows the connection between the junction boxes 310—310' and 20 the oil circuit breaker contacts junction boxes 313—313'. The latter junction boxes are also indicated by corresponding reference numerals in Figure 14. The bus conductors are connected within these latter junction boxes 313 and 313' 25 to switching contacts of the oil circuit breakers 314 and 314'. Numerals 99 and 99' designate the switching mechanism for the oil circuit breakers 314 and 314', respectively. The circuit leaves the switching arrangement within these 30 junction boxes, and is then connected to the bus conductor extending longitudinally overhead on the structural framework, by way of suitable junction boxes such as the ones shown in Figures 14 and 19 and designated by the numerals 315 35 and 315', or, as in case of the junction boxes 313 and 313' directly into the couplings 316 and 369, respectively, which will be described presently.

The switching arrangement shown in the lower 40 half of the sectionalizing bay in Figure 14 is slightly different and may best be described by following the connections from the current transformer box 215 by way of the bus tubing 309 into the junction box 312, and from there into 45 the junction box 317 in which the switching connections are made to the corresponding oil circuit breaker. Leaving the junction box 317, the circuit continues by means of flanged connections provided between the junction box 317 and the 50 junction box 318 (which is similar to the junction boxes 315 and 315') where the cross conductor is joined to the bus conductor extending longitudinally to the framework in overhead position. This latter junction box 318 has a flange connection for attachment of a junction box such as 319. A flexible tube such as 320 is attached to the junction box 319 by means of suitable flanges. The flexible tube 320 is connected to the housing of the potential transformer designated 60 in Figure 14 by numeral 321. The bus conductor branches thus to the potential transformer by means of the junction box 319 and the flexible tubing 320 which is connected by flanges on one side to the junction box and on the other side 65 to the housing of the potential transformer. It will be understood, of course, the tube 320 may or may not be flexible as desired.

The circuits in the sectionalizing bay are best explained with reference to Figure 18. The left 70 hand section of the single line diagram shown in Figure 18 illustrates the connection for the sectionalizing bay discussed above in connection with respect to its physical details.

Referring now to Figure 18, and particularly 75

to the left hand section which shows the sectionalizing bay, it will be seen that the conductor 322 which extends, in the direction of the arrow, to a reactor bay in the next bus section, is connected to a transformer 323 (located in one of the current transformer boxes such as 215, 216, 217 shown in Figures 14 and 16). A conductor 324 which may be housed within one of the enclosing tubings such as 306, 308 or 309, connects the current transformer 323 with a switching point 325 located within one of the oil circuit breaker junction boxes such as 313 or 317. The right angle bend which connects the conductor 324 to the switching point 325 is made within one of the junction boxes such as 310, 311, or 312 shown in Figure 14. The circuit breaker is designated by numeral 326. The circuit leaves the oil circuit breaker at the switching point 327, which is also located within one of the oil circuit breaker junction boxes as described. A junction designated by reference numeral 328 is provided and the bus conductor 329 continues, in Figure 18, towards the right longitudinally to the structural framework in overhead position and enclosed in suitable casings from one junction box to the other. The current transformer 330, shown in Figure 18, is indicated in Figure 14 by the reference numerals 331 and 332.

The junction 328, it will be understood, is made in a junction box such as the one indicated in Figure 14 by reference numeral 318. The conductor 334 continues, it will be recalled, from the junction point 328, in Figure 18, through a junction box such as 319, shown in Figure 14, and through a tube such as 320 into the housing 321 of the potential transformer. Reference numeral 335 designates a fuse, 336 is a resistor, and 337 is the potential transformer. The fuse is also indicated in Figure 14 by numeral 335. Similar fuses are provided with the other potential transformers.

The other side of the circuit, Figure 18, shows the conductor 338, extending in the direction of the arrow to the reactor bay in the next bus section, terminating in the sectionalizing bay in a pot head box and continuing to the transformer 339. This transformer may be housed in a current transformer box such as the one indicated in Figure 14 by reference numeral 215'. The circuit continues now as is shown in Figure 18, by way of a conductor 340 to the switching point 341. The conductor 340 may be housed within the tubing 309' shown in Figure 14 as connecting the junction box 312' with the oil retaining housing 285'. The right angle bend, in Figure 18, connecting the conductor 340 to the switching point 341 is contained in the junction box 312' shown in Figure 14. The switching point 341, shown in Figure 18, connects the conductor 340 to the oil circuit breaker 342 and from there to the switching point 343. It will be understood, that the switching points 341, 343 are contained in the corresponding junction box such as 317' indicated in Figure 14. Leaving the junction box 317' in Figure 14, the conductor goes through a junction box 318' in which is made the connection to the longitudinally extending bus bar 345 (Figure 18) which is disposed longitudinally to the general arrangement in overhead position and supported in sheathings between the various junction boxes. The current transformer 346, shown in Figure 18, is indicated in Figure 14 by the reference numeral 347 and a similar current transformer is shown at 348 in Figure 14 representing

the current transformer of the adjoining phase conductor.

Referring now again particularly to Figure 14, and continuing the description of the physical structure of the arrangement, it will be understood that the connection for each phase conductor is essentially the same, that is to say, junction boxes such as 319, 349, 344 are provided for attachment of the tubing such as 320, 320', and 321' which leads to the various potential transformer housings as described. The equipment on the other side of the switching arrangement is also similar for each phase, connecting each phase conductor to the corresponding bus which extends longitudinally in overhead position on the structural framework. The manner of joining the longitudinally extending buses and their enclosures at the bay division, will be described later.

I shall describe next the novel junction box for making the connection from the bus conductor to the potential transformer, the novel box being shown in Figure 14 at 319, 344, and 349. This novel junction box is shown in the Figures 30 and 31, which I will now describe.

Referring to these Figures 30 and 31, it will be seen that the novel junction box consists of a casting having a body 350 which is provided with a flange 351 for receiving the cover 352 having a corresponding flange 353. Each of the flanges 351 and 353 is provided, as is particularly seen in Figure 30, with holes such as 354 which register when the cover is attached to the flange 351 of the body 350. A gasket such as 355 is provided between the two flanges in order to make an oil tight joint. Ordinary bolts and nuts may be used for attaching the cover 352 to the flange 351 of the casing 350. Two flanged tubing projections 366 and 367 are provided on the casing for attachment of the junction box to suitable flanges on the corresponding junction boxes such as 318 or 313 (Figure 14), and to the flanged tubing such as 320, 320', 321' shown in Figure 14. This junction box is self-supporting between the tubing and the corresponding junction box on the structural framework.

Referring again to Figure 14, it will be seen that I have provided at the bay divisions, that is, where the sectionalizing bay shown in Figure 14 joins the feeder bay, and where the feeder bay joins the generator bay shown in Figure 15, a bus enclosure coupling generally designated in this Figure 14 by the numerals 316, 368, 369, 370, and 509, 510, 511, 512. This bus enclosure coupling includes a bus coupling and is particularly shown in detail in the Figures 67, 68, and 69 which will now be referred to for a description of its structure.

The various bus sections disposed longitudinally overhead on the structural framework are furnished in standard lengths, as will be remembered, and are enclosed in suitable sheathing extending between the various junction boxes within the respective bays. At the bay divisions, the bus sections are coupled together and the sheathing is also coupled in such a manner as to be readily accessible and also to provide for accessibility to the bus coupling.

The coupling shown in Figure 67 is particularly devised for providing a junction between a bus enclosing pipe and a junction box. Examples of such couplings as actually used in the general arrangement are shown in Figure 14 by the couplings 366 and 368.

Figure 68 represents a coupling between two bus enclosure pipes. Examples of the latter cou-

pling are illustrated in Figure 14 at 368 and 370.

Referring now particularly to Figure 67, it will be seen that the bus sections 371 and 372 are joined at 373 by means of a bus coupler which is particularly illustrated in detail in the Figures 65 and 66. It will be best to describe the bus coupling with reference to these Figures 65 and 66 before continuing the description of Figures 67 to 69, inclusive.

- 10 It will be seen from Figures 65 and 66 and also from the Figure 67, that the bus coupling comprises two pairs of clamps 374 and 375, each consisting of two members such as 376 and 377 shown particularly in Figure 65. A copper braid 378 extends between the pairs of clamps 375 and 374 for providing a good metallic contact between the clamp members. This copper braid also furnishes a certain flexibility for expansion and contraction between the bus sections 371 and 372 when the bus coupling is attached to the bus sections as shown in Figure 67. The corresponding bus sections as attached to the bus coupling are designated in Figure 66 by the reference numerals 371' and 372' corresponding to the numerals designating the bus sections in Figure 67. The attachment of the bus coupling clamps is by means of bolts such as 379 and 380 and nuts 381 and 382. It is, of course, understood that each of the pairs of clamps is fastened by means of four bolts and corresponding nuts as is shown in Figure 66. No reference numerals have been applied to the nuts in Figure 66 for the sake of keeping the drawings as simple as possible.
- 35 Again referring to Figure 67, it will also be seen that each of the bus sections 371, 372 is provided with moulded insulation such as is particularly indicated in connection with the bus section 371 and designated by the numeral 383.
- 40 The insulation at the ends of the bus sections are turned down at the points of joining the same by means of the bus coupling as explained above. The insulation is removed at the ends of the bus sections, and, since the ends are metallically coupled by means of the bus coupler comprising the clamps 374 and 375, this section of the continuous bus would be exposed in the absence of any insulating provision. For the purpose of insulating this exposed section of the continuous bus, I have provided an insulating sleeve 384 which is attached to the insulated portions of the bus sections by means of a sleeve ring such as 385, and covers the metallically exposed bus coupler. An opening 386 is provided in the sleeve support 385 in order to provide for oil circulation through the bus joint.

It will be seen that the bus coupling, as described above, presents various advantages. One of its virtues is simplicity of construction. It provides for contraction and expansion of the bus sections due to the copper braid 378 interposed between the clamp members 374 and 375. The insulation on the jointed bus sections is interrupted at the point of junction, but the metallically exposed section where the buses are joined is covered by an insulating sleeve 384, which restores the continuous insulated condition of the bus.

70 The bus enclosure coupling between a junction box and a bus pipe section as represented in Figure 67, comprises a tubular member 387 provided with flanges 388 and 389. Attached to the tubular central body, by means of bolts and nuts as shown in Figure 67, is a tubular flanged member 390, and the latter member, by means of the

flange 391, is attached to a flanged tubular connection on the junction box indicated at 392.

Gaskets such as 393 and 394 are interposed between the flanges which attach the tubular member 390 on the one side to the flange 388 of the bus enclosure 387 and on the other side to the flange 395 at the junction box 392. The attachment of the bus enclosure 387 to the junction box is, therefore, oil tight.

Arranged within the tubular flange member 390 which is interposed between the junction box and the central body of the bus enclosure 387 is a permanent oil stopper 396 for preventing oil circulation from the bus enclosure to the junction box. An insulating sleeve 397 is provided for maintaining a good insulation between the bus and the shell of the tubular sheath member 390. The stopper 396 has a dual function. It centers the bus and also prevents oil circulation from the bus enclosure to the junction box. The stopper being of cork or the like, is not considered to constitute perfect insulation between the bus bar and the sheathing and the insulating sleeve 397 is intended to provide such insulation. The provision is similar as discussed in connection with the oil retaining housing.

The junction box 392 is provided with valve 398 connecting to the oil system of the equipment. A similar valve 399 is provided in the tubular bus enclosure 387 which is used in conjunction with the valve 400 in the oil retaining housing 404 for circulating oil or filtering oil through the bus enclosure coupling. A tubular coupling member 401 provided with a flange 402 is attached, by means of bolts and nuts to an alignment joint 403 which was particularly discussed in connection with Figures 42 and 43. The purpose of this alignment joint 403 is, it will be remembered, to provide for a certain flexibility which is used in the expansion and contraction of the bus enclosure. A detailed description of the alignment joint 403 is thought unnecessary at this point of the specification in view of the detailed description furnished in connection with the Figures 42 and 43.

Attached to the flanged alignment joint 403 is the flanged oil retaining housing 404. This oil retaining housing has also been discussed previously in connection with the Figures 40 and 41 and a detailed description of the same will therefore be omitted at this point. However, attention is called to the fact that the alignment joint is attached in oil tight relation on the one hand to the flange 402 of the tubular bus enclosure 401 by means of the gasket 405, and is also connected in oil tight relation to the oil retaining housing 404 by means of the gasket 406 interposed between the flange of the alignment joint 403 and the corresponding flange of the oil retaining housing 404.

Attached to the other flange 407 of the oil retaining housing 404 is a mounting ring 408, which holds the pipe section 409 to the oil retaining housing 404. A groove is for this purpose provided in the mounting ring 408 which engages an annular projection 410 pressed into the pipe section 409 as shown in the drawings, Figure 67. The end of the pipe section 409 flares flange-like at 411 and is engaged by the rear wall of the mounting ring 408 for attachment to the flange 401 of the oil retaining housing 404. This latter attachment of the pipe section 409 to the oil retaining housing is also made oil tight by means of interposing a gasket 412. Within the oil retaining housing 404 is the permanent oil stopper 396.

413 holding the insulating sleeve 414 as already discussed in connection with the description of the oil retaining housing shown in Figures 40 and 41. The purpose of the valve 400 which operates in connection with the valve 389 for filtering or for circulating oil through the bus enclosure coupling will be remembered. The attachment 415 on the oil valve housing is connected to the oil supply. The valve 416 is closed 10 during the shipment of the equipment in order to hold oil in the pipe section 409. In operation, the valves 400 and 416 are normally open in order to secure the oil supply to the pipe section 409 on the one hand and to bus enclosure coupling 15 on the other hand.

The junction provided between the tubular bus enclosure members 387 and 401 separates the bus enclosure coupling members in insulated relation from each other but provides an oil tight joint between the same. An angular ring or flanged sleeve member of insulating material, designated by numeral 417 is slipped over the coupling member 401 and a number of packing rings such as 418, 419, and 420 are likewise slipped over the tubular member 401. This can be seen best in Figure 69. An annular projection 421 is provided on the inside of the tubular member 387. When the tubular member 401 is assembled to the tubular member 387, and the angular ring 30 417 with the packing members 418, 419, and 420 in place, the angular ring 417 will be pushed toward the left in Figure 67 until the packing members 418 to 420 inclusive attach to the edge of the annular projection 421 on the inside of 35 the tubular enclosure member 387. A mounting ring 422 is then attached to the insulating angular mounting ring 417. Bolts such as 423 and 424 are then drawn through registering holes in the flange 389 and in the insulating ring 417 as well 40 as in the mounting ring 422 and fastened by means of nuts such as 425 and 426 as shown in the drawings Figure 67 and also Figure 69. This manner of joining the bus enclosure members 401 and 387 provides for an oil tight joint and connects the sections of the bus enclosure in insulated relation from each other. The air vent 427 is provided on the section 387 of the bus enclosure.

It will be seen from the above discussion of Figure 67, that this figure shows two separate and distinct structures, namely, the bus coupling and the coupling of the bus enclosure.

The particular virtue of the bus coupling, it may be repeated, resides in the simplicity of joining two bus sections at the bay division; in providing for contraction and expansion of the bus sections relative to each other by the provision of a copper braid; and in the provision of an insulating sleeve which covers the metallically exposed joint where the bus sections are coupled. A further feature in connection with the bus coupling per se is represented by the opening 386 in the supporting ring 385 which permits the circulation of oil to the metallically exposed bus coupling which is covered by the insulating sleeve 384.

The novel improvement and advantages secured by the bus enclosure coupling as described above resides, first in the junction of the bus enclosure sections which join the sections securely, oil tight, but in insulated relation from each other; secondly in the provision of an alignment joint which permits contraction and expansion of the bus enclosure at the bay division; 75 thirdly in the provision of an oil retaining hous-

ing together with valve provisions which permit the circulation of the oil within the bus enclosure pipe and within the bus enclosure coupling but give the possibility of isolating the pipe from the enclosure coupling during shipment or when repair or adjustment work is necessary. All the joints are oil tight and reliable. 5

It will be appreciated that the simplicity of construction of all individual parts making the bus joint and the bus enclosure coupling contain 10 numerous features of novelty which will be appreciated without elaborate description. This simplicity of construction of all individual parts and their assembly to a whole cheapens production and reduces the cost of installation to an 15 appreciable extent.

It may also be mentioned at this point that the simplicity of construction permits standardization of all the parts used, one example of standardization being illustrated in the use of the 20 alignment joint 403 and of the oil retaining housing 404 in connection with the bus enclosure coupling. It will be remembered that the alignment joint and the oil retaining housing are also used at different places in the general arrangement of the equipment. 25

In Figure 69 is shown the lower portion of the manner in which the tubular members of the bus enclosure are joined on a somewhat larger scale. This figure illustrates particularly clearly 30 how the packing 418 to 420, inclusive, attaches to the annular projection 421 within the inside of the tubular bus enclosure 387, and how the same is held in place by the angular mounting ring 417 which is of insulating material. This ring, as 35 well as the packing, is slipped over the tubular enclosure member 401 and attached to the flange 389 of the tubular bus enclosure 387 by means of the mounting ring 422 which holds the angular insulating ring 417 to the flange 389 by means 40 of the bolts such as 424 and the nuts such as 426.

Referring now to Figure 68, this figure shows particularly a bus enclosure coupling between two bus pipes such as 409 and 428. The latter pipe may be connected to the junction box designated 45 by numeral 429. The bus enclosure coupling is in all essential detail similar to the one discussed in connection with Figure 67. Identical parts corresponding to the Figure 67 as shown in Figure 68, have therefore been designated with corresponding, primed reference numerals. 50

The bus enclosure pipe 428 is provided at each end with annular grooves 431 and 432. The ends of the pipe are rolled back flange-like at 433 and 434 in a similar manner as was discussed in connection with the coupling of the pipe 409 to the flange 407 of the oil retaining housing shown in Figure 67. A mounting ring 430 provided with a groove which can engage the annular projection 431 on the pipe 428 and the flange-like end 434 60 of the pipe 428, holds this pipe end to the flange 391' of the tubular pipe enclosure member 390'. The attachment, it will be seen, is oil tight, a gasket 435 being provided between the flange 391' and the end of the pipe 428. Attachment of the 65 mounting ring 430 to the flange 391' is by means of the usual nuts and bolts as also used in joining other parts of the assembly.

The attachment of the other end of the pipe 428 to the flange 436 of the junction box 429 is 70 carried out similarly by means of the mounting ring 437 which engages the annular projection on the pipe 428 designated by numeral 432 and also the flanged end of the pipe 428 designated by reference numeral 433. A gasket 438 is again pro- 75

vided between the flanges 436 and 437, making an oil tight joint between the pipe 428 and the junction box 429.

It will be seen that a valve 440 is provided on the tubular coupling member 390'. This valve 440 is used in conjunction with the valve 439 on the junction box 429 in order to circulate oil through the pipe 428. All other details in this Figure 68 correspond exactly to the details discussed in connection with Figures 67 and 69.

It will be remembered that I have disclosed a bus enclosure and bus coupling also in connection with the Figures 8 to 12, inclusive, explained previously. Comparing the previously described bus enclosure and bus coupling with the bus enclosure and bus coupling shown in the Figures 67 to 69, inclusive, it will at once be seen that the latter incorporates numerous improvements and simplifications which provide additional advantages over the previously described construction. The simplified structure permits, of course, simplified assembly which means saving in production and in installation. The previously discussed construction did not show any means for circulating oil through the bus enclosure, nor did it show any means for contraction or expansion of the bus sections. Of course, each of the constructions has its particular utility and virtue and may be used whenever occasion or necessity demands.

Having described the various improvements incorporated in the sectionalizing bay shown in Figures 14, 16, and 19, I shall now, for the sake of convenience, briefly summarize the various improvements, objects and features accomplished by the same, so that the novel structures which I have incorporated in the sectionalizing bay are retained in mind when reading the description of further improvements included in the other bays, which is yet to follow.

I have provided a novel cable entrance or pot head box and means for attaching the same in insulated relation to the structural framework of the equipment.

Another improvement is represented in the use of the alignment joint for connecting a cable sheathing to the current transformer box of the sectionalizing bay. The possibilities for standardization are, to some extent, illustrated by the use of this alignment joint also in connection with the novel bus enclosure coupling which was described with reference to Figures 67, 68, and 69.

Still another improvement resides in the provision of a novel current transformer and junction box, means for attaching the same to the structural framework in insulated relation therefrom, and novel connector means within the current transformer box for connecting the terminals of the transformer therein to the cable and cross conductors entering and leaving the current transformer box, respectively.

A further improvement is presented in the oil retaining housing connecting the current transformer box with the sheathing of the cross conductor. A further possibility for standardization is illustrated in the use of this oil retaining housing in connection with the bus enclosure coupling provided at the bay divisions.

Other improvements are contained in the various junction boxes interconnecting the cross conductors by way of connector and switching provisions housed therein.

A particular improvement resides in the provision of a junction box for enclosing a junction branching out from the longitudinally disposed

bus to the potential transformer by means of a tubing which, if desired, may be flexible.

A further improvement described in connection with the sectionalizing bay consists in a novel provision for coupling bus sections at the bay division in such a manner as to provide a good metallic contact in mechanically reliable manner and at the same time providing for contraction and expansion of the bus joints.

An additional improvement in connection with the bus coupling is presented by the insulating sleeve which is disposed tubularly over the bus coupling but permits the entrance of oil to the bus coupling.

A further improvement resides in the provision of a bus enclosure coupling at the bay division, which incorporates numerous improvements, such as the use of an oil retaining housing; the use of an alignment joint for permitting expansion and contraction of the bus enclosure coupling at the bay division; means for joining the bus enclosure coupling in insulated relation relative to the individual sections of the coupled bus enclosures which may be either two adjacent tubes or a junction box and adjacent tube; and in the provision for circulating oil through the coupling as well as valve provisions for isolating the bus enclosure coupling relative to the adjacent bus enclosures and junction boxes, respectively.

The various improvements noted above in connection with the sectionalizing bay are particularly characterized by simplicity of design, ease of assembly, shipment and installation, reliability in operation and service, and various advantages secured thereby which benefit production and maintenance.

The bay is constructed as a unit, as is every other bay in the arrangement. Its dimensions are reduced to standard rail road clearance so that each bay may be shipped as a completely assembled unit, filled with oil and provided with all wiring connections, ready to be set up in the field and joined with other units at a minimum amount of field work.

With the above improvements in mind, which are incorporated in the sectionalizing bay as described in the foregoing, the description of other improvements in the general arrangement can now be continued with reference to the feeder bay illustrated in Figures 14, 16, and 20.

The descriptions of the equipment incorporated in the feeder bay and in other bays will be appreciably shorter as compared with the description of the sectionalizing bay, since some of the apparatus employed have already been described in connection with the sectionalizing bay.

Referring now to the Figures 14, 16, and 20, it will be seen that the feeder bay is disposed between the vertically disposed columns or pillars 166 and 167 and, looking at the top or plan view shown in Figure 14, between the transverse girders 181 and 182.

It will be seen, particularly from Figure 20, that the pillars 167 and 167' are insulated from the column bases 450 and 451, the insulating provision being indicated by a prominent line designated in each case by the reference numerals 452 and 453, respectively.

The general arrangement of longitudinally and transversely extending cross beams for supporting the various equipment in overhead position on the vertically extending pillars has been described previously and will therefore be omitted.

It will be seen that the feeder cables such as 454, 455, and 456 terminate in the pot head boxes

such as 457, 458, and 459. These cable entrance or pot head boxes are of a general structure as the one discussed in connection with the Figures 44, 46, and 47, and are mounted on the structural framework in a similar manner.

Attached to the various pot head boxes are tubes or pipes such as 460, 461, and 462, which are of standard lengths and provided at each end with flanges for attachment to the flanged exit tubing provided on each cable entrance box and, at the other end, to the alignment joints such as 463, 464, and 465. The alignment joints used at this place in the feeder bay are each of a structure already described in connection with the 10 alignment joint used in the sectionalizing bay and particularly shown in the Figures 42 and 43. A description of the alignment joint will therefore be omitted at this phase.

Each of the alignment joints is connected to 20 a flanged entrance tubing on the respective junction box such as 466, 467, and 468. This junction box is slightly different from the junction box used in connection with the sectionalizing bay. The junction box used here may be of the structure as shown particularly in Figure 48.

Referring now to Figure 48, it will be seen that this junction box consists of a body portion 469 provided with a flange 470 to which may be attached the cover 471 by means of the flange 472 30 provided on the cover, and by means of ordinary bolts and nuts as described in connection with other junction boxes. The junction box is provided also with a flanged short entrance tubing indicated in Figure 48 by the numeral 473. A short flanged exit tubing such as 474 is provided near the upper end of the body 469 and on the rear wall thereof. The junction box is also provided, at its lower end, with ears such as 475 for attachment to the supporting beam 476. The attachment, it will be seen, is in insulated relation from the beam 476, the insulating strip provided between the ears 475 and the beam 476 being designated by reference numeral 477. Ordinary bolts and nuts, such as 478 and 479, respectively, 45 may be used for fastening the box 469 to the beam 476. Insulating washers such as 480 are interposed between the heads of the bolts and the ears 475 of the box in order to prevent metallic contact between the bolts and the box.

50 The connector used in the various junction boxes such as 468 shown in Figure 20 and also in the corresponding junction boxes 466 and 467 illustrated in the Figures 14 and 16, is shown in the Figures 38 and 39 which were described previously in connection with the detailed description 55 of the arrangement used in the current transformer boxes of the sectionalizing bay. The use of this T bus connector in the junction boxes in the feeder bay as well as in the current transformer boxes in the sectionalizing bay is a further example of the possibilities for standardizing the equipment. This principle of standardization wherever permissible, is carried throughout in the arrangement shown in the drawings and described in this specification.

I shall particularly describe, for convenience sake, only the connections of one phase conductor, namely, the one entering and leaving the junction box 468 shown in Figures 14 and 20.

70 It will be seen from Figures 14 and 20, that the conductor leaving the junction box 468 extends through an oil retaining housing 481 (the conductors leaving the junction boxes 466 and 467 being disposed within similar oil retaining 75 housings 482 and 483). The structure of this oil

retaining housing has been particularly described in connection with the Figures 40 and 41 which show an oil retaining housing also used in the sectionalizing bay and in the bus enclosure coupling used at the bay division.

It will be seen, at this point of the description, that there are several apparatus the use of which is extended to various parts in the general arrangement of the equipment in accordance with the principle of standardizing wherever standard- 10 ization is possible.

Attached to the flanged oil retaining housings of each conductor, are the standard lengths tubing 484, 485, and 486 which shield the cross conductors on the way from the junction boxes and 15 from the oil retaining housings to the transformer boxes or casings located in the center of the structural framework and designated by the reference numerals 487, 488, and 489, respectively. Connections are made within these centrally 20 located casings to transformers, meters and relays, to fuses, resistors, and to potential transformers. Connections are also made within these 25 housings to cross conductors leaving on either side of the housing to the junction boxes such as 490 and 491 disposed above the oil circuit breakers such as 492 and 493. Reference numerals 492' and 493' designate the control mechanism housings for the oil circuit breakers. These junction boxes disposed above the oil circuit breakers are 30 connected, by means of flanged tubing to the centrally located transformer casings and also to the junction boxes such as 494 and 495, respectively, which are disposed above the junction boxes such as 490 and 491, as particularly shown in Figure 35 20, and provide for making connections to bus bars extending longitudinally of the structural framework in overhead position.

Referring particularly to the Figure 14, it will be seen that the junction box 490, for example, is 40 provided with a flanged short tubing which connects to the centrally located casing 489 by way of the alignment joint 487'. This alignment joint as well as the alignment joints to the left of the same connecting the adjacent junction 45 boxes to the corresponding centrally located casings is the same as already described in connection with the Figures 42 and 43, which, it will be understood, illustrates another example of how the various apparatus are used in conformance 50 with the general idea of standardizing the equipment.

It will also be seen that the junction box 491 which is located on the other side from the junction box 490 is also provided with a short flanged 55 tubing connecting directly to a flanged tubing on the centrally located casing 489. The other side of the junction boxes 490 and 491, respectively, are also provided with short flanged tubing. The latter flanged tubings on the junction boxes 60 490 and 491 are closed, since these junction boxes connect with the bus conductors 505 and 506 which go through the junction boxes 494 and 495. However, in case of the junction boxes located in the middle of the bay, the tubings are connected 65 to the flanged short tubing on the junction boxes 499 and 500 as is shown in Figures 14 and 20. These latter junction boxes (499 and 500) are of a general shape as shown in Figure 20 and are mounted on the framework in overhead position by means of suitable supports such as 501 and 502. The junction boxes such as 499 and 500 join the cross conductors from the oil circuit breakers to the bus bars extending longitudinally 70 of the framework. The bus bars are designated in 75

the Figure 20 by the reference numerals 503—505 and 506—508, the first group designating the main bus and the second group indicating the reserve bus.

5 The bus conductors disposed in one level transversely to the general arrangement and indicated in Figure 14 by the reference numerals 504, 505, 507, and 508, are shown exposed at the bay division and correspond to the similarly numbered conductors in Figure 20. The bus conductor 503, viewing the arrangement in Figure 14, is disposed beneath the conductor 504, and the conductor 506 is located below the conductor 507 as is particularly indicated in Figure 20.

15 It will also be seen from Figure 14 that I have provided bus coupling and bus enclosure couplings at the bay division to the right of the feeder bay. A portion of the bus enclosure couplings 509 and 510 is shown in the Figure 14 with the conductors 504 and 507, respectively, extending from the partially shown couplings. The couplings for the conductors 505 and 508 are shown only fragmentary with the conductors 505 and 508 projecting from the flanged tubular coupling members 511 and 512. The manner of coupling the bus conductors at the bay division and the manner of coupling the bus enclosures at the bay division is the same as already described in connections with the bus couplings 368—369, 316—318 shown at the division of the sectionalizing bay and feeder bay. The bus coupling and the bus enclosure coupling, it will be remembered, are particularly shown in the Figures 67, 68, and 69, and have been described previously. An entire run of a bus extending longitudinally in overhead position on the structural framework between the various junction boxes and other apparatus, including the enclosure couplings at the bay division, will be described later on.

40 A single line diagram illustrating the circuit connections in the feeder bay is shown in Figure 18. It will be seen from this figure, by referring to the physical structure shown in Figures 14, 16, and 20, that a feeder such as the one designated 45 by the numeral 456 in Figure 20, and by numeral 513 in Figure 18 enters the system through a cable entrance box, by way of a tubing and alignment joint, a junction box, an oil retaining housing and a suitable tubing as was described previously, until 50 it reaches the junction point 514, shown in Figure 18, where a connection is made to an instrument transformer such as 515 and on the other side to a fuse such as 516, connecting then over a resistor 517 to the potential transformer such as 518. 55 The fuses are indicated in Figure 14 by the reference numerals 516, 516', and 516''. The instrument transformer, the fuse, resistor and potential transformer, as well as the necessary connections diagrammatically illustrated in Figure 18 are 60 housed in the centrally located casing supported in overhead position on the structural framework as shown in Figures 14 and 20, and described previously. A connection is made between the transformer 515 and the switching points 519 and 65 520 of the oil circuit breakers 521 and 522 at point 523. This connecting point, it will be remembered, is also housed in a centrally located casing supported on the structural framework. The contact points 519 and 520, however, as well as 70 the contact points 524 and 525 are housed in junction boxes disposed above the oil circuit breakers, such as the boxes 490 and 491, shown in Figure 20. The conductors 526 and 527 leave the junction boxes of the oil circuit breaker and enter the corresponding junction boxes such as 494—495, or 75

such as 499—500, shown in Figure 20, where connections are made with the longitudinally extending bus bars such as designated in Figure 18 by numerals 528 and 529, leading to the generator bay. The bus 528 may be the reserve bus, and 5 the bus 529 may be the main bus in the system.

10 The physical structure of the generator bay is illustrated in the Figures 15, 17, and 21. It will be seen, particularly from Figure 15, that this bay extends between the transverse beams 183 and 184, and, viewed from the side, as shown in Figure 17, between the vertically disposed columns or pillars 168 and 169. The Figure 21 is taken on line 21—21 in Figure 15 and shows a view into the 15 interior of the generator bay.

15 Referring now to the Figures 17 and 21, it will be seen that the cables terminate in the cable entrance or pot head boxes such as 533, 534, and 535, which are mounted on the beams 536 and 537 in insulated relation therefrom. The structure 20 of the cable entrance box is particularly shown in Figures 44, 46, and 47, which have been described previously. The attachment of the boxes to the structural framework is also the same as described in connection with these figures. The attachment 25 of these cable entrance boxes to the framework is also illustrated in Figure 27 which is taken on line 27—27 in Figure 21, looking in the direction of the arrows. The reference numerals applied in Figure 27 refer to like parts shown in the 30 Figures 17 and 21. A detailed description of Figure 27 is therefore omitted. It will be seen, however, that these cable entrance or pot head boxes are mounted on the structural framework in insulated relation therefrom. It will also be 35 seen from Figure 17 and Figure 27 that each of the boxes is provided with three flanged entrance tubings at its bottom, and two exit tubings, flanged in like manner, at its upper wall. Only one exit tubing is utilized. The boxes are stand- 40 ardized so that they may be used on either side of the frame work and for various bays.

45 The connections within the pot head box 535, shown in Figure 21, and also within the pot head boxes 533 and 534, shown in Figure 17, exhibit 45 several improvements which are particularly illustrated in Figures 55, 56, 60, 61, and 62.

50 The connector provision designated by numeral 538 in Figure 21 will be described first with reference to the Figures 60, 61, and 62.

55 Referring now to the Figures 60, 61, and 62, the connector shown in these figures is particularly adapted in cases where three outgoing cables are used as is the case in the generator bay. Figure 60, it will be seen, is a top view with the 55 bus conductor 796 in cross section; Figure 61 is a side view taken on line 61—61 in Figure 60; and Figure 62 is a sectional view taken on line 62—62 of Figure 60.

60 The cables are attached within the pot head 60 assemblies 777, 778, and 779. Attached to the contact studs 780, 781, and 782 are rigid contact cross blades 783 and 784. The attachment is by means of spacers such as 785 and 786 as shown in Figure 60. These cross blades and spacers are 65 clamped to the contact studs 780, 781, and 782 by means of bolts and nuts as shown in the drawings. Braided flexible link conductors such as 787, 788, 789, and 790, and a set of similar flexible braided link conductors adjacent thereto as indicated by 70 numeral 791, in Figure 61, are attached at one end to the blades 783 and 784 by means of bolts and corresponding nuts as shown. Each of these flexible braided conductors is provided at each end with a metallic member for attachment 75

to the blades 783 and 784 as described, and, at the other end, for attachment to the arms such as 782 and 783 of a clamp structure comprising two members 784 and 785 which are attached to the bus 786 by means of bolts and nuts. This clamp connector comprising the section 784 and 785 may be of a general structure as the one shown in Figures 55 and 56 which I will describe next.

It will be seen from Figures 55 and 56 that the clamp connector comprises two separate members 550 and 551, which are fastened around the bus conductor 539 and attached thereto by bolts such as 554 and 555 and nuts 556, 557, 558, and 559. The arms 552' and 553' are shown extending both to the same side from each of the clamp members. The arms 552' and 553' correspond to the arms 784 and 785 shown in Figures 60, 61, and 62. Each of these arms 552' and 553' is provided with holes such as 560—561, 562—563. These holes are provided for receiving the bolts which attach the various braided conductors to the arms 552' and 553'.

Continuing the description now with reference to the Figures 17 and 21, it may be mentioned at this point that the feeder bay and the generator bay are identical except for the direction of the incoming circuit and current transformer connections. Standard length tubing is provided around the bus conductor rising from each pot head box such as 535. It will be understood, of course, that the sheathing 565 and 566 shown in Figure 17 corresponds in all respects to the tubing 564. Each of these tubings is provided with flanges at each end for attachment to the cable entrance boxes such as 535 and, on the other end, for attachment to the alignment joints 567, 568, and 569, respectively. These alignment joints are in all respects the same as already discussed in connection with the other alignment joints used in the sectionalizing and in the feeder bays and particularly illustrated in Figures 42 and 43. A detail description of these alignment joints is therefore omitted at this point of the specification. Any details as to these alignment joints and the structure thereof may be had from the description of Figures 42 and 43.

Each of the alignment joints is provided with flanges and the upper flange is attached to a flanged short entrance tubing on each of the junction boxes such as 570, 571, and 572. The structure of the junction boxes may be the same as that described in connection with the Figure 48. The mounting of the junction boxes to the support on the structural framework is also the same as that already described.

A connection 573 is indicated within the junction box 572 shown in Figure 21. This connection which is made between the vertically rising bus conductor within the tubing 564 and the cross conductor 574 disposed within the tubing 575, corresponds in all respects to the T bus connector structure which I have described in connection with the Figures 38 and 39.

Oil retaining housings 576, 577, and 578 are connected to the junction boxes 570, 571, and 572, respectively, as is shown in Figures 15 and 21. The oil retaining housings have been described already in connection with Figures 40 and 41.

I again desire to call attention to the fact that the various equipment which I have disclosed in this case lends itself to standardization of parts which is particularly evidenced by the repeated use of certain apparatus and parts throughout the general arrangement.

Attached to the flanged oil retaining housings

576, 577, and 578 are standard length tubings 575, 576, and 580, each leading to and being attached to flanged tubings 581, 582, and 583, respectively, on each of the centrally located current transformer and potential transformer boxes 584, 585, and 586.

The current transformer box 585 is shown with the cover removed in Figure 15. The section through the current transformer box shown in Figure 21 illustrates the interior and various improvements incorporated in such a current transformer box, which I will describe in detail with reference to the open box shown in Figure 15 and to the section of the box in Figure 21. I have, for convenience of description sake, designated the equipment in these boxes by like reference numerals.

Referring to the open casing in Figure 15 designated by numeral 585, and also to the Figure 21 in which a casing is shown in section, it will be seen that such a casing encloses a current transformer such as 587, to which a cross conductor may be connected, such as disposed within the tubing 580. A branch conductor 588 is attached to the cross conductor in front of the current transformer 587 which leads to the potential transformer 589 and to various other equipment to be described later. The other terminal of the current transformer 587, it will be seen, is connected to the cross conductor 591 by means of a branch connector 590. The cross conductor 591 extends between the junction boxes 592 and 593 located above the oil circuit breakers such as 594 and 595 shown in Figure 21. Numerals 594' and 595' designate the control mechanism for the oil circuit breakers. The connection between the centrally located casing 585 and the junction boxes 592 and 593 is made by means of flanged tubing such as 596 and 597 extending between the junction box 593 and the casing 585 and by means of an alignment joint 598 disposed between flanged short tubing and the casing 585 and on the junction box 592, respectively.

This alignment joint 598 is, again, the same as described previously in connection with Figures 42 and 43 and its use between junction boxes illustrates a further example of the flexibility of the various apparatus disclosed which is particularly adapted to standardization.

The cross conductor 591 enters the junction boxes 592 and 593 respectively, as described, where it is joined to switching contacts of the oil circuit breakers. One such connection is illustrated in Figure 21, showing the cross conductor 591 as it joins the contact cap of one of the switching contacts of the oil circuit breaker 594. The other end of the cross conductor 591 which enters the junction box 593 of the oil circuit breaker 595 is, of course, also connected to a switching contact of the oil circuit breaker 595, in a similar manner as the connection is made to the switching contact cap of the top of the oil circuit breaker 594.

Each of the oil circuit breakers 594 and 595 has of course two switching contacts. The companion switching contact cap in the oil circuit breaker 595 which is disposed within the junction box 593 (Figure 21) is shown in Figure 21 and designated by the numeral 600. The connection between this latter switching contact and the corresponding bus bar within the junction box 601 is indicated in Figure 21 to be made by means of an offset right angle bus connector 602'.

Now, before continuing the general description of the physical structure, it will be well to refer

to certain novel details employed within the transformer box 585 and within the various junction boxes.

Referring particularly to the current transformer casing 585 which is shown with the cover removed in Figure 15 and in section in Figure 21, it will be seen that the current transformer 587, lies in the same plane with the cross conductor 591. This arrangement, it will be remembered, is somewhat similar to the one already explained in connection with Figures 3, 4, and 5. It gives the advantage of interchangeability for making the connection at either side of the current transformer and at the same time gives the possibility of reducing the dimensions of the difficult casting of the centrally located transformer housing. The interchangeability of making connection with the current transformer from either side thereof adapts this bay unit to be used either as a generator or as a feeder bay.

Reference numeral 602 in Figure 15, it will be recalled, designates a clamp connector for attaching the branch conductor 588 which leads to the various equipment connected in series with the potential transformer. This connector 602 is the same as the connector described in connection with the Figures 36 and 37 employed in the transformer box of the sectionalizing bay, which is illustrated in the Figures 34 and 35.

The parallel bus connector designated by numeral 590 in Figures 15 and 21, which connects the current transformer to the cross conductor, is particularly shown in Figures 63 and 64 which will now be described in detail.

Numeral 591 in Figure 63 may correspond to the cross conductor 591 shown in Figures 15 and 21. This conductor, as will be remembered, extends to the switching contact within the junction box 592 leading to the circuit breaker 594. The conductor 591' shown in Figure 63 extends to the junction box 593 and to a switching contact of the circuit breaker 595 therein. The conductor 603 shown in Figures 63 and 64 represents the terminal of the current transformer 587 in Figures 15 and 21.

It will be remembered that the current transformer 587 as is shown in Figures 15 and 21, is connected with the cross conductor 591 by means of a connector 590. From Figures 63 and 64, in which like reference numerals have been applied to like parts, it will be seen that the parallel bus connector consists of two parallel portions 590 and 590'. At each end of these parallel members there is a clamp-like structure integral therewith for receiving the conductor 603 and the ends of the conductors 591 and 591', respectively. The two parallel sections of the bus connector 590 are clamped together on the conductors 590-590' and 603, respectively, by means of bolts such as 608, 609, 610, and 611, and nuts such as 604, 605, 606, and 607.

It will be seen that this parallel bus connector as described above is extremely simple and permits removal or attachment at any time desired. All that is necessary for gaining access to the equipment located within the transformer casing such as 585 is to remove the corresponding cover from the casing and to expose the equipment as is shown in Figure 15. The current transformer 587 and all the connections are then accessible.

The bus connector for the contact caps 599 and 600 shown in Figure 21 is particularly illustrated in the Figures 49 and 50.

Referring now to Figures 49 and 50, it will be seen that the contact cap on the oil circuit

breaker switching equipment, designated in Figure 50 by numeral 612, is provided with ears such as 613 and 614. Attached to these ears are links such as 615, 616, 617, and 618. Each of these links comprises two metallic members such as 619 and 620 shown in connection with the link 618, and these metallic members are, in each instance, connected by means of a braided conductor. The attachment of the links to the contact cap such as 612, is by means of ordinary bolts and nuts as is shown in the drawings. The bus connector comprises a split clamp body such as 621 having a suitable boring for receiving the bus conductor such as the conductor 622, the clamp being split and adapted to surround the conductor as shown. This clamp body is attached to the cross conductor 622 which may correspond to the conductor 591 shown in Figure 21 and is fastened thereon by means of bolts such as 623 and nuts such as 624 and 625. It will be seen particularly from Figure 49, that there are two such bolts provided for attaching the split clamp body 621 to the corresponding conductor 622. This split clamp is provided with ears such as 626 and 627 which are provided with suitable holes. Attached to these ears are the metallic members such as 619 of the various links such as 615 to 618, inclusive, the attachment being made by means of bolts such as 628 and 629 and nuts such as 630 and 631.

It will be seen that this bus connector for the contact caps such as 599 and 600 shown in Figure 21, is extremely simple in construction and provides for all the features necessary in connection with such a bus connector, that is, firm and reliable attachment with the flexibility which is desired and necessary.

The bus connector 632 shown in Figure 21 as connecting the contact cap of one of the oil circuit breaker contacts to the bus bar 633 is particularly shown in the Figures 51 and 52 which I will explain next.

As will be seen from these figures, the contact cap such as 634, which leads to a switching contact as shown in Figure 21, is provided with ears 635 and 636. These ears are cast on the contact cap and correspond to the ears 613 and 614 described in connection with the arrangement shown in Figures 49 and 50. Attached by means of bolts and nuts such as 637-638 and 639-640, respectively, are pairs of links such as 641-642, 643-644. Four pairs of such links are fastened to each of the ears, such as 635 and 636 of the contact cap, as is particularly shown in the Figure 51, the pairs of links being designated in this figure by the numerals 641, 645, 646, and 647. It will be seen, that the attachment of these links is, in each instance by means of bolts and nuts as particularly shown in Figure 52. Each of the links comprises, as in the case of the links described previously, a braided conductor provided at each end with a metallic strip or bracket. The brackets are provided with suitable holes which register with corresponding holes on the ears 635 and 636 for receiving the bolts which fasten the links to the ears on the contact cap.

The connector leading from the contact links on the contact cap to the bus bar such as 633, designated in Figure 21 by the same reference numeral, consists of two angular members 648 and 649. Each of these angular members, at its lower end is suitably formed and provided with ears such as 653 and 654. These ears are provided with suitable holes for receiving the bolts such as 655 and 656 for attaching the corre- 75

sponding links 644 to 647, inclusive, at each side of the ears 653 and 654. The attachment of the links to the ears of the angular connector is again by means of nuts such as 657 and 658 as is shown 5 in Figure 52. The two members 648 and 649 are fastened together at their lower end by means of a bolt 650 which is drawn through a suitable hole in the members 648 and 649 and attached thereto by means of 651. A spacer washer 652 10 is interposed between the members 648 and 649 in order to provide a rigid structure.

The upper ends of the members 648 and 649 which are curved in an angle of 90° from the arms 648 and 649 are spaced so as to provide a 15 clamp-like structure for receiving the bus conductor 633. The attachment of the connector to the bus is by means of ordinary bolts and nuts such as 659—660, and 661—662. Two bolts and corresponding nuts are provided on each 20 side of the clamp structure of the connector as is particularly indicated in Figure 52, the bolts in this figure being marked by the reference numerals 660 and 660' and the nuts by numerals 662 and 662'.

25 It will be observed that the connector for the contact cap as described above with reference to the Figures 51 and 52, has certain features in common with the connector described in connection with Figures 49 and 50. Each of these 30 connectors establishes connection between a bus bar or cross conductor, respectively, by means of flexible braided links. The contact cap is in each instance of the same structure, being provided with ears cast on the cap for attaching the flexible links of the connector. The attachment of the connector as such to the corresponding 35 bus conductor is in each instance by a clamp-like structure which surrounds the bus conductor firmly, providing a good metallic connection between the connector and the corresponding bus. The structure is in each instance characterized by utmost simplicity of design intended to reduce the cost of production and to facilitate assembly and installation. As a further advantage of the simplicity of construction of the connector may be mentioned the ease with which the connector can be put in place, which, it will be appreciated, represents an asset in the question of maintenance.

50 Again referring to the Figure 21, it will be seen that the contact cap 600, the structure of which was particularly described in connection with the Figures 49 and 50, is connected to the bus bar 663 by means of a short cross conductor 664 and a bus connector 602'. This latter bus connector will now be described with reference to the Figures 53 and 54.

It will be seen from the Figures 53 and 54 that 55 the bus connector comprises two members 665 and 666 each of which is offset at a right angle. Each end of each of the members 665 and 666 is formed into a clamp-like structure, the clamp structure of the member 666 being indicated by the reference numeral 667 and 670, while the clamp structure of the member 665 is indicated by the reference numerals 668 and 669. These clamp structures of the members of the offset members 666 and 665 are put on the corresponding conductors 664 and 663, respectively, (these conductors being indicated by like reference numerals in the Figure 21) and attached thereto by means of ordinary bolts and nuts. Four bolts and nuts, respectively, are employed for attaching the clamp structures of the members 665 and

666 to the corresponding conductors, the bolts which attach the connector to the bus bar 663 being indicated by the reference numerals 671 and 672, while the bolts for attaching the connector to the conductor 664 are indicated by the reference numerals 673 and 674. The corresponding nuts are designated by the reference numerals 675, 676, 677, and 678. A transformer connection is indicated at 667'. 5

This connector, as all previously described 10 structures serving a similar purpose, is simple in structure and can be easily manufactured and assembled. It is, by its simple structure, adapted for mass production and for standardization.

Referring now again particularly to Figure 21, 15 it will be seen that I have provided an insulator bushing or cylinder 634' and a similar bushing 599' around the switching contacts of the oil circuit breaker 594 which are located within the junction box 592. Similar bushings are, of 20 course, provided within the junction box 593 which houses the contacts of the oil circuit breaker 595, and a like bushing is provided around the contact of the potential transformer as designated by reference numeral 589'. These bushings 25 insulate and protect the contacts properly and in a simple manner.

The circuit connections which obtain in the generator bay described with reference to the Figures 15, 17, and 21, and as maintained by the 30 various connecting means explained in the foregoing discussion of the generator bay, are shown in the single line diagram in Figure 18. The generator bay, it will be remembered, is adjacent the feeder bay and is shown in Figure 18 35 as the third from the left on the drawings Figure 18.

This single line diagram of the generator bay shown in Figure 18 will be described with referring back to the Figures 15 and 21, respectively, 40 wherever such reference is necessary in order to illustrate the physical location of the various connections shown in the diagram in Figure 18.

The generator cable 679 is shown terminating in the general equipment at the point 680. Now, 45 referring back to the Figures 15 and 21, this connection may lead through one of the cable entrance or pot head boxes provided on the structural framework, such as the cable entrance box 535. Connections are made within this cable 50 entrance box between the cable conductor and the conductor rising from the cable entrance box within the sheathing such as 564 and through the alignment joint such as the joint 569 into the junction box such as 572. The cross conductor 55 such as 574 (Figure 21) is connected within the junction box 572 to the conductor rising within the sheathing such as 564 by means of a T bus connector disposed within the junction box, and the cross conductor continues then through an 60 oil retaining housing such as 576 and through a sheathing such as 575 to the centrally located transformer box such as 584, 585 or 586 shown in Figure 15. The junction point 680 shown in 65 Figure 18 is located within the transformer box. This junction point 680 may correspond to the junction point 602 shown in Figures 15 and 21. It will be seen that a branch conductor 588 is shown in the Figures 15 and 21 as branching off 70 from the point 602 (680 in Figure 18) leading to other equipment within the transformer box and specifically, as is shown in Figure 18, to the fuse 682 and from there over the resistor 683 to the potential transformer 684. The fuses are 75

indicated in Figure 15 by the reference numerals 682, 682', and 682''.

- Examining the Figures 15 and 21 again, it will be seen that a current transformer 587 is connected to the junction point 602. This current transformer may correspond to the current transformer designated in Figure 18 by the reference numeral 685. It will also be seen from Figures 15 and 21 that a conductor 591 interconnects the equipment located in the junction boxes 593 and 592 located above the oil circuit breakers, such as shown in Figure 21 and designated by numerals 594 and 595. This cross conductor may be connected within the junction boxes 592 and 15 593 to the switching contacts such as 686 and 687 shown in Figure 18. The connection between the current transformer 685 and the cross conductor connecting the switching points 686 and 687 is made, as shown in Figure 18, at the point 688. 20 20 The conductor which connects the current transformer 685 to the point 688 may be a parallel bus connector such as the one shown in Figures 15 and 21 and designated there by the reference numeral 590. 25 25 The circuit leaves the oil circuit breakers and terminates in switching contacts such as 689 and 690, shown in Figure 18. Connection is made between these switching contacts and the bus bar sections 691 and 692 by means of bus connectors 30 which may be of a structure such as is shown in Figure 21 and designated there by the reference numerals 602' and 632. The bus bar sections 691 and 692 may correspond to the bus sections 633 and 663 shown in Figure 21. The connections 35 35 may be made within junction boxes 601 and 601' in Figure 21, the point of contact being indicated in Figure 18 by the reference numerals 693 and 694. The bus bars continue through suitable bus couplings and bus enclosure couplings at the bay 40 division to the reactor bay which is shown at the right in Figure 18 and to the feeder bay, respectively, shown at the left of the generator bay.

Bus enclosure couplings 680, 681, 682, and 683 are shown in Figure 15 located at the bay division 45 between the generator bay and the reactor bay. These bus enclosure couplings are structurally and functionally the same as the one described previously with reference to the Figures 67, 68, and 69. The bus enclosures at the division 50 between the generator bay and the feeder bay (at the left of Figure 15), are shown dismounted, with the bus conductors 684, 685, 686, and 687 projecting therefrom. These bus conductors will be coupled with the corresponding bus conductors 55 507, 508, 505, and 504 shown at the right of Figure 14 at the division between the feeder bay and the generator bay. The coupling of these bus sections is made as was previously described with reference to the Figures 67 to 69, inclusive 60 and the bus enclosures at the division of the feeder bay and the generator bay which enclose the bus couplings are shown partially in Figure 14 and designated by the reference numerals 509, 512, 511, and 510 and partially in the Figure 15 65 designated in this figure by the reference numerals 688, 689, 690, and 691.

The physical structure of the reactor bay, shown in Figures 15, 17, and 22, will now be 70 explained in detail. It will be seen from Figures 15 and 17 that the reactor bay extends between the cross beams 185 and 186, respectively, mounted on the vertically disposed columns such as 169 and 170 in Figure 17 and extending between 75 the columns 170 and 170' as shown in Figure 22,

which is a side view taken on line 22—22 in Figure 15.

Before entering the detailed description of the various novel structures in the reactor bay, I desire to call attention to a few details, which are 5 incorporated in the structural framework at the bay division between the generator bay and the reactor bay.

Referring to Figure 24, for example, which is a section on the structural framework taken on line 24—24 in Figure 15, this figure shows by way of example the manner in which the cross beam such as the cross beam 185 is disposed on the vertically extending columns or pillars. Figure 24 will be described in conjunction with the Figure 25 which is a sectional view on the framework taken on line 25—25 of Figure 15.

Reference numerals 692 and 693 designate the girders extending longitudinally to the general arrangement shown in Figures 14 and 15, between the vertically disposed columns or pillars. The cross beam designated in Figure 24 by the numeral 694 corresponds to one of the beams extending transversely at the bay division between the columns. Numerals 695 and 696, respectively, 20 25 may correspond to the columns or pillars 169 and to the companion column on the other side of the general framework opposite the column 169. It will be seen that I have provided triangular braces such as 697 disposed in the corner 30 where the girder 694 joins the column 695. Similar braces such as 698 shown in Figure 24 and the braces 699 and 700, respectively, are attached to the vertical columns and to the longitudinally extending beams such as 692 and 693, 35 respectively, and fastened thereto. Numeral 701 in Figure 24 designates a longitudinal beam in section.

In Figure 23 I have shown a sectional view into the reactor bay taken on line 23—23, in 40 Figure 15, to illustrate the arrangement of various junction boxes and cross conductors, that is to say conductors, the enclosures of which extend transversely to the bay shown in Figure 15. Referring now to Figures 15 and 23, it will 45 be seen that I have mounted on the supporting plate 719 which, in turn, is mounted on the girders such as 718, three junction boxes such as 705, 708, and 712. The bus enclosure 680 at the bay division between the generator and the reactor 50 bay connects with the junction box 708 (Figure 15) by means of a short standard length tubing designated by the reference numeral 710. A bus enclosure coupling 714, at the bay division, located in Figure 15 under the bus enclosure 680, 55 as shown in Figure 23, connects with the junction box 712. The bus enclosure coupling 681, in Figure 15, at the bay division between the generator bay and the reactor bay connects directly, by means of a short standard length tubing 720 60 with the junction box 721 located above an oil circuit breaker, such as the one shown in Figure 22 and designated by the reference numeral 722.

Now, again referring to Figures 15 and 23, it 65 will be seen that the cross conductor from the junction box 723 in Figure 15 connects by way of the oil retaining housing 703 and by way of a tubing 724 with the junction box 725. In the Figure 23, only a section through the oil retaining housing 703 is shown since this figure is taken 70 on line 23—23 in Figure 15 and shows only the essential details in connection with the various cross conductors and the junction boxes. The oil retaining housing 704 shown in Figures 15 and 23 connects between the junction box 726

and the junction box 705. Branching off from the junction box 705 is a short flanged tubing which connects with a junction box 706. The structure of this latter junction box 706 will be described presently with reference to the Figures 32 and 33. Connection is made within this junction box with a conductor leading through a tubing such as 727, to the potential transformer and to various other equipment, as will be seen later.

10 The oil retaining housing 707 shown in Figures 15 and 23 connects the junction box 728 with the junction box 737 by means of a tubing 728'. The oil retaining housing 708 shown in Figures 15 and 23 connects the junction box 731 with the junction box 708. At the bottom and in the rear wall of this latter junction box 708 is a short flanged tubing connecting to a junction box 729 as shown in Figure 23, in which a connection is made to the potential transformer and to other equipment, the conductor leading thereto being disposed within the tubing 730. This junction box 729 is similar to the junction box 706. The oil retaining housing 711 connects the junction box 732 with a tubing which is directly connected by means of the usual flanged pipe to the junction box 733. Accordingly, only the section of the oil retaining housing 711 is shown in the Figure 23. The oil retaining housing 713 connects the junction box 734 with the junction box 712. This latter junction box is connected to another junction box 735 in which a connection is made to the potential transformer through the tubing 736.

35 The junction boxes 706, 728, and 735 are of the same construction and will be described later on in detail. Each of the junction boxes 705, 708, and 712 is mounted by means of a standard such as 715, 716, and 717, respectively.

There are various points which may be noted 40 in connection with the above description of the Figure 23 and the corresponding references made to Figure 15. The cross conductors, it will be observed, are all disposed in one plane running transversely to the general arrangement and 45 connecting the various junction boxes on the structural framework in overhead position. The above description also illustrates how the bus enclosures such as 680 and 714 are connected with the junction boxes such as 708 and 712. It 50 will be recalled that I have previously described two structures of bus enclosure couplings in connection with the Figures 67 to 69, inclusive. One bus enclosure coupling, namely, the one shown in Figure 67 is provided for connecting the 55 bus enclosure coupling directly to a junction box. This particular structure may be used in connection with the bus enclosure coupling 714 which connects directly to the junction box 712 as is shown in Figure 23. The other structure of a 60 bus enclosure coupling, shown in Figure 68, illustrates a case where a junction box is coupled to a tubing and the tubing is connected to the box enclosure coupling. This latter structure may be used in connection with the junction box 708 65 which is joined with the bus enclosure coupling 680 by means of the tubing 710 shown in Figure 23.

I shall now describe the structure of the junction box, such as 706, 729, and 735, shown in Figure 15 and particularly in Figure 23, with reference to the Figures 32 and 33.

This junction box serves the purpose of housing a branch connection or junction leading from a bus bar to a potential transformer by way of a 75 suitable tubing as is shown in Figure 15, and is

for this purpose attached to a junction box which houses the bus bar and in which connection is made from the bus bar to a cross connector. This junction box, as far as its purpose is concerned, is the same as the junction box shown on the same sheet of drawings, in Figures 30 and 31, which is used in the sectionalizing bay and has been described previously. The structural difference between the two junction boxes is a result of their use. In the sectionalizing bay, a 180° junction is required, while in the reactor bay, due to different location of the equipment, a 90° junction is necessary.

Accordingly, the junction box shown in Figures 32 and 33 comprises a body 880 provided with a 15 flange 881 for the attachment of the cover 882 which is provided with a flange 883. A gasket 884 is interposed between these flanges in order to make an oil tight joint. Holes, such as 885 are provided in the flanges for receiving suitable 20 bolts which are fastened by means of suitable nuts as usual.

The box is provided with three flanged tubings 886, 887 and 888 as shown. The tubing 887 will be attached to the corresponding junction box 25 from which the above mentioned conductor branches out, and this conductor is connected, within the junction box shown in Figures 32 and 33, to a conductor entering either through the short flanged tubing 886 or through the tubing 30 888. The tubing through which the conductor enters the junction box, is attached, by means of its flange, to the flange of a suitable tubing in which the conductor is housed. I have provided two exit tubings on this junction box in order to 35 adapt the same for use on either side of the equipment on the structural framework. The conductor, branching off from this junction box by way of a flexible tubing, leads to a potential transformer and to other equipment as will be 40 detailed later on. The exit tubing not used, will be closed oil tight by means of a suitable cover.

It will also be observed that I have positioned the entrance tubing 887 on one side of the body 45 of the box. This particular shape makes the casting simpler and gives the advantage of making the connection within the box in a more convenient manner than would be the case if the tubing were positioned in the center.

Continuing the description of the general structure, it will be seen from Figure 15 that the junction box 737, located between the junction boxes 733 and 725 is shown with the cover removed, exposing the interior and a connector 55 50 therein which connects the cross conductor from the junction box 729 with a junction box in which the switching contacts of an oil circuit breaker are located. The connector shown in the interior of the open junction box 737 in Figure 15 may be the same parallel bus connector which has been discussed in connection with Figures 63 and 64, which illustrates a further example of the standardization which I have carried through wherever possible.

I shall now describe further details in the general arrangement of the reactor bay with particular reference to Figures 15, 17, and 22. It will be seen that the cables 739, 740 and 741 as well as similar cables on the other side of the 70 general arrangement, such as 741' as shown in Figure 22, terminate in cable entrance or pot head boxes such as 752, 753, 742, 754, 755, and 744. The cables entering in boxes, such as 754, 755, 744, lead to the reactors and the cables 75

entering through the boxes, such as 752, 753, 742 arrive from the reactors and also maintain connection with the sectionalizing bay of the next bus section. The structure of the cable entrance boxes may be similar to the structure described in connection with the Figure 44, and their attachment to the structural framework may also be the same as has been described previously.

Figures 28 and 29 show top views of the various cable entrance boxes as taken on the lines 28—28 and 29—29, respectively. Specifically, the Figure 28 shows a top view of the junction boxes 754, 755, and 744, while the Figure 29 shows a top view of the junction boxes such as 752, 753, and 742. The circles shown on the left of the junction boxes 752, 753, and 742 in Figure 29 designate sections of the cables rising on the side of these junction boxes and entering the junction boxes 754, 755, and 744. The circles shown on the right side of the latter junction boxes shown in Figure 28, designate the conductors disposed in suitable tubing rising from the junction boxes 752, 753, and 742 which are located below the junction boxes 754, 755, and 744. The attachment of the various junction boxes shown in Figures 28 and 29 is, it will be remembered, in insulated relation from the structural framework and in a manner as was previously discussed in connection with Figure 44. The numerals 169 and 170 in Figures 28 and 29 designate sections through the vertically disposed columns 169 and 170 shown in Figures 17. The lower row of cable entrance boxes in Figure 17, is mounted between the columns 169 and 170 on the supporting girders such as 756 and 757 and the upper row of cable entrance boxes such as 754, 755, and 744 is mounted on similar girders designated in Figure 17 by the numerals 758 and 759. The attachment of the junction boxes to these girders is, as described previously, in insulated relation therefrom.

It will be seen from Figure 22, that I have provided connector means within the cable entrance boxes as particularly illustrated in connection with the boxes 742 and 745 which are shown partially broken away to expose the interior and the connectors disposed therein. These connectors in the cable entrance boxes may be of a structure such as shown in the Figures 57, 58, and 59.

In Figure 57, it will be seen, is represented a top or plan view of the connector within the cable entrance box, while Figure 58 represents a section on line 58—58 in Figure 57, and Figure 59 a sectional view on line 59—59 in Figure 57.

Numeral 539 in Figures 57 to 59, inclusive, indicates the bus conductor rising from the cable entrance box such as 535 in Figure 21. Reference numerals 540, 541, 542, and 543 represent the pot head assembly within the cable entrance box. From the pot head assembly rise the contact studs, such as 544, 545, and 546, as shown in the Figures 58 and 59. There are connector provisions for joining the contact studs with the bus conductor 539. One of these provisions is a clamp connector having laterally projecting arms, which is attached directly to the bus conductor. This clamp connector is shown on a larger scale in the Figures 55 and 56 which were described previously.

Continuing now the description of Figures 57 to 59, inclusive, it will be seen that the conductors rising from the pot head assemblies 542 and 543 are connected by means of a link 547 which is attached to the corresponding conductors by

means of bolts and nuts as shown. These conductors are further connected by means of a link 548 as is particularly shown in Figure 58. The conductors 546 and 545 are connected by means of a link 549 as is particularly shown in Figure 59. Attached to the bus 539 are companion clamp members 550 and 551 having arms 552, 553. The attachment of the clamp members 550 and 551 is by means of bolts such as 554 and 555 and nuts such as 556, 557, 558, and 559, as explained in connection with Figures 55 and 56. Clamped to the arms 552 and 553 and the links 548 and 549 which are connected to the conductors 544 and 545, respectively, are braided conductors such as the conductors shown in Figures 58 and 59 and designated by the numerals 558', 559', 560, and 561. These braided conductors are in pairs as is particularly evident in Figure 58 which shows the companion conductor to the conductor 561, designated by numeral 561' and also the companion conductor 559'' lying behind the conductor 559' as shown in Figure 59.

It will be understood that the braid connection as discussed in connection with Figures 57, 58, and 59 merely illustrates the possibility of making the required connections. Other combinations may be devised by utilizing the general arrangement and what it teaches.

Although the pot head connector described above differs slightly from the one described in connection with Figures 60, 61, and 62, the basic similarity of structure will be apparent. The arrangement provides in either case means for attachment to a bus conductor, means for attachment to cable conductors, means for joining the cable conductors, and flexible means for joining the bus conductor with the cable conductor.

Continuing the description now with reference particularly to the Figures 15 and 17, it will be seen that I have provided junction boxes on either side of the structural framework and supported thereby in overhead position. These junction boxes are designated in the Figures 15, 17, and 22 by the reference numerals 723, 726, 728, 45 731, 732, 734, located in one row on the right side of the structural framework (seen from Figure 22) and the junction boxes 746, 747, 748, 749, 750, and 751 located in overhead position on the opposite side. Each of these junction boxes 50 may be of the same general structure as the one described in connection with Figure 48. The attachment of each of the junction boxes to the structural framework is likewise the same as that discussed in connection with Figure 48.

Attached to the flanged short tubing projecting from the bottom of each of the junction boxes is an alignment joint such as indicated by the reference numerals 797 and 798 in the Figures 17 and 22. This alignment joint is the same as 60 that described in connection with Figures 42 and 43 and its purpose is, as in the previously described cases, to provide for a neat alignment as well as expansion and contraction of the bus enclosing tubing attached thereto and connecting the corresponding cable entrance and pot head boxes.

It will be seen from Figure 17 that relatively short tubings such as 760, 762, and 764 are provided between the pot head boxes 754, 755, and 744 and the corresponding alignment joints attached to the junction boxes 746, 748, and 750. Correspondingly longer tubings 761, 763, and 765 are provided between the cable entrance boxes 752, 753, and 742 and the corresponding alignment 75.

5 joints. The tubing is, of course, connected to the various alignment joints and also to the junction boxes and shields the bus conductor disposed therein and leading to the various junctions as shown. The connection between the bus conductors, rising through the vertically disposed tubings to the various junction boxes, and the cross conductors disposed in right angle thereto and running transversely toward the 10 center of the general arrangement (Figure 15) is made within the junction boxes by means of T bus connectors such as the one shown in the Figures 38 and 39 which were described previously in detail.

15 Oil retaining housings such as the ones indicated by reference numerals 703, 704, 707, 709, 711, 713, and 800 (the latter located opposite the oil retaining housing 703) are attached to the rear walls of each of the junction boxes as particularly 20 shown in Figures 15 and 22. These oil retaining housings are of the general structure discussed in connection with Figures 40 and 41. A description thereof is therefore omitted at this place of the specification.

25 Standard length tubings enclosing the corresponding cross conductors connect the alternate junction boxes on either side of the structure to the junction boxes such as 801, 802, 803, 725, 731, and 733. The connection between the junction 30 box 751 and the junction box 801 is particularly shown in Figure 22. Within the latter junction boxes (such as 801) are made connections between conductors leading to switching contacts of the oil circuit breakers. One of the junction 35 boxes, namely, the junction box 737, in Figure 15 has been shown with the cover removed to illustrate the connection. The connector used in the junction boxes, such as 737, may be the same parallel bus connector already described in connection with Figures 63 and 64. Leaving the junction box in which the oil circuit breaker contacts are located, the cross conductors continue through suitable tubings provided between the junction boxes such as 721 and 803 and connecting 40 to the junction box in which a connection is made to the longitudinally extending bus bar and by way of another junction box to the cable leading to the reactor. The circuit connections will be described later on with reference to Figure 18 and cross reference to Figures 15 and 22. However, before presenting the description of the circuit connections in detail, I desire to call 45 attention to a bus connector for a contact cap shown in Figure 22 and designated by the reference numeral 804. The structure of the bus connector designated by numeral 721' in Figure 22, may be the same as described with reference to Figures 49 and 50.

50 The connector 804 establishes connection between the contact cap to the circuit breaker switching contact designated by the reference numeral 806, and the bus bar 805. The structure of this connector is particularly shown in Figures 70 and 71 which I will now describe in detail.

55 It will be seen from Figures 70 and 71 that the bus connector shown in these figures is somewhat similar to the bus connector shown in Figures 51 and 52, which has been described in connection with equipment of the generator bay. Reference 60 numeral 807 in Figures 70 and 71 designates the contact cap disposed within the junction box such as 803 in Figure 22 and leading to the switching contact of the oil circuit breaker 808. This contact cap is provided with ears 809 and 810 65 cast integrally with the cap 807. Suitable holes

are provided in each of the ears 809 and 810 for attachment, to each of the ears, of four pairs of flexible links 811, 812, 813, and 814. Each of these links comprises two members such as 814 and 815 shown in Figure 71. Pairs of flexible 5 links are similarly provided and attached to the ear 810 of the contact cap 807 as shown in Figure 71 by the reference numerals 816 and 817.

Each of the links consists of a flexible braided conductor provided at each end with a metallic 10 member such as is indicated in connection with the link 814 in Figure 71 by the reference numerals 818 and 819. Four such pairs of links are attached to each of the ears such as 809 and 810 of the contact cap 807 by means of bolts such as 15 820, 821, 822, and 823, and nuts such as 824 indicated in Figure 71. The links on the other side of the structure, as shown in Figure 71, are attached similarly by means of bolts and nuts.

20 A split clamp member 825, provided with ears 25 826, 827, 828, and 829, is attached to the cross conductor such as 830 by means of bolts such as 831 and 832 and corresponding nuts 833 tying the split clamp portions 834 around the conductor 30 830. Suitable holes are provided in the ears 826 to 829, inclusive, for the attachment of the flexible braided links for each ear on one side, and for the attachment of similar pairs of links such as 835, 836, 837, and 838 to one of the upper ears, as well as for the attachment of similar 35 pairs of links such as 840 and 841 to the companion ear. The structure of these links is similar to the links connecting the clamp member with the contact cap and the attachment to the ears of the clamp member is also the same. 35

Two angular members, having ear-like extensions such as 844 and 845 and being formed at the other end to provide a clamp-like structure such as indicated by the reference numerals 846 and 847, are attached to the flexible braided link 40 conductors as is shown in the drawings. The bus bar such as 805 is surrounded by the clamp-like ends 846-847 of the angular members 842 and 843 which are attached thereto by means of bolts and nuts as shown. 45

It will be seen from the above description of Figures 70 and 71 that the bus connector for the contact cap used in the reactor bay differs in its construction from the bus connector used in the generator bay and illustrated in Figures 51 and 52 in the provision of an additional clamp member such as 834 which is interposed between and conductively connected with, the contact cap 807 and the angular connector comprising the parts 45 842 and 843. This additional clamp is necessary 55 in the reactor bay because of the provision of the bus conductor such as 830 which branches off at this point of the circuit to the reactor. It will be seen that the elements of the bus connector shown in Figures 70 and 71 with the exception of the 60 additional clamp member 825 are the same as those shown in Figures 50 and 51. This is in keeping with the general thought of providing simplified equipment which lends itself to standardization, and, accordingly, to mass production. 65

I shall now describe the circuit connections obtaining in the reactor bay with reference to the Figure 18, and shall refer, whenever necessary, to the physical structure of the equipment as shown in the Figures 15 and 22. 70

The bus bar 692 shown in Figure 18 may be disposed within the pipe 849 shown in Figure 15 which attaches to the bus enclosure coupling 682 at the bay division between the generator bay and the reactor bay. A transformer for bus cable 75

- differential relays, such as 848, is shown connected to the bus bar which continues then into the junction box 803 where the switching contacts for the oil circuit breaker and other connections are located. As is particularly shown in Figure 18, located in the junction box such as 803 are the switching contacts 849 and 850 leading to the circuit breaker 889, which is indicated in Figure 22 by reference numeral 808. The junction point 851 is likewise located within a junction box such as 803 and is physically represented by the bus connector for the contact cap indicated in Figure 22 by the numeral 804 and specifically described with reference to the Figures 70 and 71. The branch connection 852, in Figure 18, leads from the bus connector to the junction box 750 shown in Figure 15 and from there by way of the various connections in the cable entrance box such as 744 (Figure 17) to the reactor such as 853, shown in Figure 18.
- The circuit continues then by way of the connections indicated in dotted lines and designated by the reference numeral 854 to the sectionalizing bay in the next bus section, with a branch connection 855 leading from the reactor 853 and by way of the cable entrance box such as 742 and the junction box such as 751 in the Figures 15, 17, and 22, to the junction box such as 801 (Figure 15) in which a parallel bus connector is located which connects the conductor 855 with a cross conductor leading to the switching contact 849 of the oil circuit breakers 889. The parallel bus connector located in the junction box such as 801 has been described with reference to Figures 63 and 64 and is also schematically indicated in Figure 15 which shows the cover removed from the junction box 737 exposing the parallel bus connector 738. The arrangement in the other junction boxes, such as 801 is, of course, similar.
- The reserve bus 691 shown in Figure 18 which extends between the generator bay and the reactor bay may be disposed within the pipe 720 which, as is shown in Figure 15, connects with the bus enclosure coupling 681 at the division between the generator bay and the reactor bay. A transformer such as 866 (Figures 15 and 18) for bus cable differential relays is connected to the bus 691 before the same enters the junction box 721 (Figure 15) in which connection to the oil circuit breaker and other connections are located. Specifically, the bus is connected within the junction box 721 to the switching contact 867 (Figure 18) leading to the oil circuit breaker 890, which may correspond to the one designated by numeral 722 shown in Figure 22. A branch connection 868 leads from the junction point 869 (Figure 18) through a junction box 706 (Figure 15) and through a suitable tubing 727 to the junction box 870 shown in Figures 15 and 22 where the branch conductor 868 (Figure 18) is connected to the fuse 871 and is wired from the fuse over the resistor 872 to the potential transformer 873. The fuses are indicated in Figure 15 by numerals 871, 871', and 871''.
- The switching point 869 shown in Figure 18 is similar to the switching point 851, that is to say, a bus connector such as 804 shown in Figure 22 joins the bus within the junction box in the manner described in connection with Figures 70 and 71 and provides for a branch connection 876 which continues by way of the junction box such as 726 and the corresponding cable entrance box to the reactor shown in dotted lines in Figure 18 and designated by the numeral 877. A branch connection 878 similar to the branch connection

854 leads to the sectionalizing bay in the next bus section with a conductor 874 leading through a cable entrance box and through a junction box, such as 723 in Figure 15, by way of the pipe 724 and the oil retaining housing 703 to the junction box 725 in which a connection is made by means of a parallel bus connector as the one shown in Figures 63 and 64 and also illustrated in Figure 15 in open junction box 737 to the junction box 721 which houses the oil circuit breaker switching contact 875 as shown in Figure 18.

I shall now follow the entire circuit connections shown in Figure 18 by tracing the location of the circuit as disposed in the physical structure shown in Figures 14 and 15. Various points discussed in the foregoing description will be briefly recalled, and the improvements incorporated in the entire structure will be mentioned in tracing the entire circuit through the physical structure so that the salient features of the invention may be easily remembered and located.

Referring now to the Figure 18 the circuit of which will be traced in the physical structure of the general arrangement shown in Figures 14 and 15, the conductor 338, which connects the bus section shown in Figure 18 with the reactor bay in the adjacent bus section, is wired into the sectionalizing bay shown in Figure 14 by way of a novel pot head or cable entrance box (shown in the Figure 44) and enters a novel current transformer box such as shown in Figure 14 by the reference numeral 217' (the current transformer box being particularly shown in the Figures 34 and 35, its mounting being indicated in the Figure 45). A current transformer for instruments such as the one indicated in Figure 18 by the reference numeral 339 is disposed in the junction box such as 217'. Novel connectors are used in this junction box in a manner shown particularly in Figures 34 and 35 and the details illustrated in the Figures 36, 37, 38, and 39. The cross conductor 340 shown in Figure 18 continues then physically (in Figure 14) by way of an oil retaining housing such as 283' which is shown in detail in the Figures 40 and 41. The conductor terminates by way of a sheathing in a junction box such as 310' shown in Figure 14. Connection is made within this junction box 310' to a cross conductor leading into the junction box 313' in which is located the oil circuit breaker switching contact 341, shown in Figure 18. The circuit goes through the oil circuit breaker 342 to the other switching contact 343 which is also located in junction box 313' (Figure 14) and connects to the bus bar disposed longitudinally to the general arrangement in Figures 14 and 15 and located, at this point, being at the bay division, within the bus enclosure coupling 316 (Figure 14). The bus is coupled within this bus enclosure coupling 316 in a manner particularly illustrated in the Figures 60, 65, 66, and 67. The bus enclosure coupling 316 in which the bus coupling is disposed is shown in detail in the Figures 67, 68, and 69. It will be seen, also from the Figure 14, that the bus coupling 316 comprises various sections and specifically two enclosure sections, an alignment joint, and an oil retaining housing. The alignment joint which is also used at various other points for example preceding the junction box 217', through which the cable from the adjacent reactor bay enters the sectionalizing bay, has been particularly described with reference to Figures 43 and 42. The oil retaining housing it will be remembered, has been explained with reference to Figures 40 and 41. The bus enclosure coupling 75

surrounds the coupled bus sections at the bay division and continues to a transformer or bus cable differential relay which is indicated in the Figure 14 by the reference numeral 348. The same reference numeral 348 is applied to this current transformer in the Figure 18.

The bus 345 in Figure 18 continues then to the feeder bay by way of a suitable tubing 346 shown in Figure 14 and enters a junction box in the 10 feeder bay. In this junction box 491 shown in Figure 14 are located the switching contacts 524 and 519 shown in Figure 18 as connecting to the oil circuit breaker 521. A current transformer for instruments, meters, and relays is disposed 15 within the junction box 489 in Figure 14, the current transformer being indicated in the Figure 18 by the reference numeral 515. Connection is made within this junction box 489 at a point 523 (Figure 18) with the current transformer 515, the 20 fuse 516, the resistor 517 and the potential transformer 518. A branch connection is also made in this junction box to the feeder cable leaving the feeder bay as is indicated by the reference 25 numeral 513 in Figure 18.

The feeder cable is disposed physically as is shown in Figure 14, within the tubing 484, goes through the oil retaining housing 481 into the junction box 468 and then by way of an alignment joint and a cable entrance box to the corresponding equipment. The bus continues then 30 from the junction box 491 in Figure 14 to the generator bay shown in Figure 15. The connection, it will be seen from Figure 15 is made by way of a bus enclosure coupling such as 689 at 35 the bay division in which the bus section 508 (Figure 14) is coupled with the bus section 685 shown in Figure 15.

The bus 528 shown in Figure 18 continues within the generator bay in overhead position from 40 the bus enclosure coupling 689 (Figure 15) by way of the tubing 689' and enters the junction box 593'. Within this latter junction box 593' in the generator bay are located the switching points 694, 689', and 686 shown in Figure 18. 45 These switching points connect the bus conductor with the corresponding oil circuit breaker 595.

A novel bus connector for contact caps has been described previously in connection with the junction box such as 593' (Figure 15) and with 50 particular reference to the Figures 51 and 52. A cross conductor leads from the junction box 593' in Figure 15 to the centrally located transformer box 586. Within this transformer box are made 55 connections to a current transformer for instruments, meters and relays, the current transformer being indicated in Figure 18 by the reference numeral 685. A connection is also made from the current transformer 685 within the transformer box 586 to a fuse 682, to a resistor 60 683, and a potential transformer such as 684. The branch conductor 679 in Figure 18 leaves the transformer box 586 shown in Figure 15 through a tubing 575, by way of an oil retaining housing 576 and a junction box 572 in 65 which a connection is made with the generator conductor by means of a T bus connector which has been particularly described with reference to Figures 38 and 39. The generator cable 679 (Figure 18) leads then through an 70 alignment joint and through a cable entrance box in which connectors are disposed which have been explained with reference to the Figures 55—56, and 60, 61, and 62.

The bus conductor 691 in Figure 18 continues 75 physically from the generator bay to the bay

division where it is coupled within the bus enclosure coupling 681 shown in Figure 15. This bus enclosure coupling and the bus coupling within the same are of the same construction as already discussed previously. The bus enclosure 5 coupling 681 in Figure 15 is connected to a tubing 720 enclosing the bus conductor on its way to the reactor bay.

The bus conductor 691 is connected in the reactor bay to a current transformer or bus cable 10 differential relay as indicated in the Figure 18 and also in the Figure 15 by the reference numeral 866. The bus conductor continues from the current transformer 866 within suitable sheathing into the junction box 721 (Figure 15). Within 15 this junction box are located the switching contacts 867 and 875 (Figure 18) of the oil circuit breaker 890 and also the junction point 869. This junction point 869 is, it will be remembered, identical with the novel bus connector for the contact cap as shown in Figures 70 and 71. A branch connection 868 (Figure 18) leads by way of a novel junction box 706 in Figure 15 and by way of a suitable tubing 727 into the centrally located casing which houses the fuse 871 (Figures 15 20 and 18), the resistor 872, and provides for connection with the potential transformer 873. From the switching point 869 (Figure 18) which is located within the junction box 705 in Figure 15 branches the conductor 876 to the reactor 877. 30

The branch conductor 876 (Figure 18) goes through an oil retaining housing 704 (Figure 15), through a junction box such as 726, through an alignment joint, through suitable tubing, through a pot head box in which a braid bus connector 35 such as the one shown in Figures 57, 58, 59 is located, and then through the reactor 877 as shown in the diagram in Figure 18. The branch conductor 878 leads to the sectionalizing bay of the next bus section and the conductor 874 (Figure 18) 40 enters the reactor bay by way of a cable entrance box, suitable tubing, and alignment joint, a junction box such as 723 (Figure 15) and oil retaining housing such as 703, suitable tubing such as 724, and the junction box 725. Within the latter is 45 disposed a parallel bus connector as described in connection with Figures 63 and 64, provided for connecting the conductor 874 (Figure 18) to the switching contact 875 of the corresponding oil circuit breaker in the reactor bay which is housed 50 in the junction box 721 in Figure 15.

The circuit of the main bus shown in the lower half of Figure 18 will now be traced in its physical relation with reference to Figures 14 and 15 in a similar manner as the circuit of the reserve bus 55 was traced above.

As will be seen from Figure 18, the circuit of the main bus enters the sectionalizing bay from the reactor bay in the next bus section. The cable enters the sectionalizing bay through a 60 cable entrance or pot head box, through a suitable tubing, and alignment joints, and enters the novel current transformer box mentioned previously. This current transformer box is shown in Figure 15 by the reference numeral 217. It 65 houses the current transformer 323 shown in Figure 18 which is provided for instruments. The circuit continues then by way of a current conductor 324 (Figure 18) which goes through an oil retaining housing 283 (Figure 14), through a tubing 706 and enters a junction box 310. This junction box 310 is connected to the junction box 313 which houses the switching contacts 325 and 327 (Figure 18) of the oil circuit breaker 326.

A novel junction box is attached to the junc- 75

tion box 313 designated in Figure 14 by the reference numeral 344, and connecting to a suitable tubing 321' which leads to a centrally located casing such as 322'. Within this novel junction 5 box and the suitable tubing is disposed the conductor 334 shown in Figure 18 connecting within the centrally located casing 322' (Figure 14) to the fuse 335 (Figure 18), to the resistor 336, and to the potential transformer 337.

10 Attached to the junction box 313 in Figure 14 is the bus enclosure coupling 369 within which are coupled the sections of the bus 329 at this bay division. The bus coupling and the bus enclosure coupling 369 in Figure 14 are, of course, of the 15 structure previously described and repeatedly mentioned.

15 The bus 329 in Figure 18 continues then within the bus enclosure coupling and connects to a bus cable differential relay current transformer 20 330. This current transformer is also shown in Figure 14 and designated by the same reference numeral. The bus continues from the current transformer 330 through a tubing 330' which terminates in the junction box 490 in the feeder bay. 25 Connection is made within this junction box 490 between the bus 329 (Figure 18) and the circuit breaker switching contacts 520 and 525.

25 The switching contact 520 is connected to a current conductor which leads through the transformer housing 489 in Figure 14 to a switching contact of the oil circuit breaker located on the other side of the general arrangement in Figure 14 and provided for the reserve bus. It will be seen from Figure 14 that this current conductor 30 is disposed within an alignment joint 397 located between the transformer casing 489 and the junction box 490. The connections within the transformer box 489 in Figure 14 have been described previously with reference to the reserve bus shown 35 in Figure 18. The bus 529 in Figure 18 continues then from the feeder bay to the generator bay.

40 It will be seen from the Figures 14 and 15 that a bus enclosure coupling and bus coupling is disposed at the bay division between the feeder bay 45 and the generator bay within which the bus 529 (Figure 18) is coupled in the usual manner described previously. The two bus sections of the bus 529 in Figure 18, which are coupled at this bay division, are designated in the Figures 14 and 50 15 by the reference numerals 505 and 686, respectively. The bus enclosure coupling 690 in Figure 15 which encloses the bus coupling of the sections 505 and 686 is connected to a tubing 690' within which is disposed the corresponding section of the bus 529 shown in Figure 18.

55 The bus 529 continues through the tubing 690' (Figure 15) to the generator bay where the tubing 690' is attached to the junction box 592'. Within this latter junction box are located the switching 60 contacts of the oil circuit breaker designated in the Figure 18 by numerals 687 and 690. The switching point 693 is also located within this junction box 592' and it will be remembered that this switching point is represented physically by 65 the bus connector for the contact cap shown in Figures 51 and 52.

70 The junction box 592' in Figure 15 is connected by way of an alignment joint to the centrally located transformer casing 586 in which 75 are located the current transformer 685 (Figure 18) and the other equipment for connecting the cross conductor between the oil circuit breakers to the potential transformer, as described previously in connection with tracing the circuit of the reserve bus.

The bus sections of the generator bay and the reactor bay of this particular phase conductor are joined at the bay division within the bus enclosure coupling 682 shown in Figure 15. This coupling, as well as the bus coupling enclosed 5 therein, are of the same structure as previously explained.

The bus section 692 (Figure 18) continues within the bus enclosure coupling 682 (Figure 15) and within the tubing 849 shown attached to the 10 bus enclosure coupling 682. A current transformer 848 is shown in Figure 15 and also in Figure 18 and designated by the same reference numerals. This transformer is provided for bus cable differential relays. The bus continues from 15 the transformer 848 to the junction box 803 (Figure 15) in the reactor bay. Within this junction box 803 are located the switching contacts 849 and 850 (Figure 18) of the corresponding oil circuit breaker 889 and also the switching point 20 851. The latter, it will be remembered is represented physically in Figures 70 and 71 showing how the connection to the bus conductor is made and how the branch conductor 852 (Figure 18) is joined to the general circuit. 25

The conductor 852 in Figure 18 leaves the junction box 803 in Figure 15 through a short tubing 803' and through an oil retaining housing, by way of a junction box such as 750, alignment joint, a tubing such as 764 (Figure 17) and a 30 cable entrance box such as 144. Within this cable entrance box are made the connections between the conductor 852 (Figure 18) and the cable leading to the reactor 853. The conductor 854 leads to the sectionalizing bay in the next bus section 35 and the conductor 855 connects with the other switching contact 849 of the oil circuit breaker in the reactor bay by way of a cable entrance box such as 142 (Figures 17 and 22), through a tubing such as 765, alignment joint such as 791, 40 junction box 751, an oil retaining housing 800 (Figure 15), a tubing 800' and a junction box 801, which in turn is connected to the junction box 803 housing the switching contact 849 (Figure 18) of the oil circuit breaker 889. 45

The above summarizing description of the circuit connections of the main bus and of the reserve bus with relation to their physical location in the general arrangement as shown in Figures 14, 15, 16, 17, 19, 20, 21, and 22 completes the 50 description of the metal clad switch gear proper.

It will be understood, of course, that I have traced the circuit of only one phase conductor. The circuit of the other phase conductors of the main bus as well as of the reserve bus are, of 55 course, similar.

I shall now furnish a detailed description of the novel provision for elevating the circuit breakers, as shown particularly in the drawings Figures 72 to 80, inclusive. 60

It will be remembered that I have shown elevator provisions for certain equipment, such as the oil circuit breakers, consisting of an elevating truck which is laterally and longitudinally movable within the structural framework of the 65 switch gear. I have shown and described this elevating truck in my copending application mentioned previously, and have also shown the same diagrammatically in Figure 2 in the present application. The elevating truck, it will be recalled, 70 is mounted on a platform which is longitudinally movable within the switch station, the truck being laterally movable on the platform, so that the same may be positioned below any oil circuit breaker in the station. When it is desired 75

- to remove an apparatus, such as oil circuit breakers, it is necessary to position the elevating truck below the same, to elevate the truck, to disconnect the oil circuit breakers from the mounting provisions, and to lower the same by means of the truck. This work is time consuming and requires a number of men. The switching and testing equipment for the oil circuit breakers is mounted stationary and, when it is desired to inspect an oil circuit breaker, it is necessary to lower the same on the elevating truck, to open its tank, and then to inspect the same, while the circuit breaker is resting on the truck. This means that the truck cannot be employed for any other work while the inspection operation is in progress. This elevating truck represents a considerable investment of money. It does not lend itself to remote control and has no guiding provisions for the circuit breakers.
- 10 In order to overcome the above mentioned and other difficulties, I have devised motor operated elevating provisions individual to a bay and adapted to elevate a plurality of circuit breakers simultaneously and independently of any other circuit breakers. This novel elevating provision may be operated from the switch house by remote control or at its place of location in the switch gear. It makes it possible to remove, install, or to inspect several oil circuit breakers at the same time, with less trouble and within a shorter time than was heretofore possible. It eliminates the expensive elevating truck and it guides the circuit breakers eliminating thereby special alignment which was heretofore necessary. The novel elevating provision eliminates testing equipment and can be used for disconnecting the circuit breakers, making special disconnect provisions superfluous. Shipment of the equipment is also simplified since the novel elevator is a part of a bay unit.
- 20 The improved elevating mechanism comprises, generally, a multi-screw mechanism provided with supporting brackets. This multi-screw mechanism is mounted in elevated position on the structural framework and may be lowered or elevated by means of a drive mechanism consisting of a motor, a worm gear for operating shafts and bevel gears which act upon the multi-screw mechanism. The supporting bracket provisions on the screw mechanism are adapted to engage supporting means which hold the circuit breakers. The oil circuit breakers, in other words, are exteriorly provided with projections which rest upon girders or supporting beams, and the latter are engaged by supporting means provided on a number of elevating screws. These screws can be lowered or elevated simultaneously by means of the motor operated mechanism mentioned above and, accordingly, when actuated in this manner, will lower or elevate the screws which, in turn, lower or elevate the supporting beams or girders supporting the circuit breakers.
- 30 The work required for elevating or for lowering an oil circuit breaker is reduced by this novel elevating provision to a minimum. It requires less manual labor and yields many other advantages which will be apparent from the following detailed description furnished with reference to the Figures 72, 73 and 74 which will be described next.
- 40 Portions of the transversely extending framework supported in overhead position are shown in the Figures 72, 73, and 74 and indicated by the reference numerals 900 and 901. A portion of the longitudinally extending framework is shown at 903. This framework is, it will be re-

membered, supported in overhead position on vertically extending columns or pillars as described previously. Positioned on this framework are supporting plates such as 902 and various cross girders for mounting the equipment such as junction boxes, etc.

5 The supporting plate 902 shown in the Figures 72, 73, and 74 is recessed at 980 in order to provide a ledge for mounting the elevating mechanism. As will be seen from the drawings, bearing members 904, 905, 906, and 907 are mounted on the supporting plate 902 on opposite sides of the recessed portion 980. Each of the pairs of bearing members supports, rotatably, a shaft 909 and 10 908, respectively. Mounted on the shaft 909, and 15 keyed to the same, are bevel gears 910, 915, and 914. Bevel gears 911, 913, and 912 are similarly mounted on, and keyed to, the shaft 908.

10 Each of these shafts 908 and 909 also supports two U-shaped brackets, such as the brackets 916 20 and 919 mounted on the shaft 909 and the brackets 922 and 925 mounted on the shaft 908. These brackets are pivotally attached to the respective shafts, the attachment to the shafts being made by the legs of the U-shaped brackets, designated 25 in the figures by the numerals 917-918, 920-921, 923-924, and 926-927. As will be seen from the drawings, the legs of the various pivotally mounted U-brackets enclose the bevel gears keyed to the shafts and designated by the numerals 30 914, 915 and 912, 913, as well as the corresponding bearing members 904, 905, 906, and 907, respectively.

35 Disposed within each of the U-shaped brackets 916, 919, 922, and 925, and at the bottom 35 thereof, is a bevel gear, designated in the drawings by the numerals 928, 929, 930, and 931. These latter bevel gears are keyed to screws such as 932, 933, and 934, as shown in the Figures 73 and 74, and mesh with the corresponding bevel gears 40 mounted within the legs of the corresponding supporting U-shaped brackets. Thus, as will be seen particularly from Figure 74, the bevel gear 931 which is keyed to the screw 933 meshes with the bevel gear 913 which is mounted within the 45 legs 924 and 923 of the U-shaped bracket 922. The bevel gear 928 which is keyed to the screw 934 meshes with the bevel gear 912 mounted within the legs 927 and 926 of the U-shaped bracket 925. These brackets and also the brackets 916 50 and 919 on the other side of the equipment are, of course, pivotally mounted on the respective shafts as was mentioned previously.

55 The driving mechanism for the screws is described below as follows:

50 Mounted on brackets such as 935 and 936 is a shaft 944 to which is attached a bevel gear 940. This bevel gear, as is particularly seen in Figure 72, meshes with the bevel gear 910 mounted on the shaft 909. Rotatably mounted in bearing 60 brackets such as 937 and 941 is a shaft 938 having a bevel gear 939. This latter gear meshes with the bevel gear 911 mounted on the shaft 908. A worm gear drive is disposed in a suitable housing, such as 945, as shown in the drawings. 65 A motor 947 is mounted on supports 948 and 949, and its shaft is connected to the pulley 946 by means of the belt 950. This motor is reversible and, when operating, actuates the worm gear which is enclosed in the housing 945, and the 70 worm gear in turn rotates the shafts 938 and 944 which are coupled to the worm gear by means of the couplings 942 and 943. Accordingly, the bevel gears such as 939 and 940 keyed to the shafts 938 and 944, respectively, will be rotated in one 75

or the other direction and will rotate the shafts 908 and 909 since the bevel gears 939 and 940 are in mesh with the bevel gears 910 and 911, respectively, which are keyed to the shafts 908 and 5 909.

- The bevel gears 912—913 and 914—915 which are keyed to the shafts 908 and 909, respectively, will therefore rotate and in turn rotate the bevel gears such as 931 and 928 (Figure 74) meshing 10 with the bevel gears 912 and 913. Since the bevel gears such as 928 and 931 (Figure 74) are keyed to the screws such as 933 and 934, these screws will rotate in one or the other direction depending 15 on the rotation of the motor 947. A set of corresponding screws are, of course, operated by the bevel gears mounted on the shaft 909 located on the opposite side of the mechanism. One of the latter screws is shown at the left in Figure 73 and designated by the reference numeral 932.
- 20 Each of the U-shaped and pivotally mounted brackets has an angular projection such as indicated in the drawings by the reference numerals 951, 952, 953, and 954. These angular projections on the U-shaped brackets are particularly 25 seen in Figure 73 in connection with the bracket 916 having the angular projection 952 and the bracket 922 having the projection 954. Pivotally mounted on these angular projections are the supporting bars 955, 956, 957, and 958. It will be 30 particularly seen from Figure 73 that the supporting bar 955 is pivotally attached to the angular projection 952 on the U-shaped bracket 916, and that the supporting bar 956 is pivotally attached to the angular projection 954 on the U-shaped bracket 922. The lower end of each of 35 these supporting bars 955 to 958, inclusive, is hook-shaped as is particularly seen in Figure 74 in connection with the supporting bars 956 and 958 shown in this figure in dotted lines. The purpose 40 of these pivotally mounted supporting bars will be described later on.

Tubular, internally threaded elevators such as 45 959, 960, and 961, shown in the Figures 73 and 74, are supported by the screws 932, 933, and 934, respectively. There are, of course, four such 50 tubular internally threaded elevators, one supported by each screw of the mechanism. When the screws are rotated, these tubular elevators will move on the screws either up or down, depending on the direction of rotation of the screws which, as will be remembered, depends on the 55 direction of rotation of the reversible motor 947.

I have shown the tubular elevators 959 to 961, 60 inclusive, in the Figures 73 and 74, internally threaded and engaging the corresponding screws only in their upper portions. It will be understood, of course, that I have shown this particular structure only for the sake of illustrating an example of how the screws may be constructed. 65 They may be threaded throughout, and may, if it is found desirable, extend farther down as I have shown in the drawings. The length of the tubular elevators may, for example, correspond to the length of the corresponding screws.

65 Each of the oil circuit breakers 970, 971, 972, is provided with brackets projecting therefrom as indicated by the numerals 962 and 963 in Figure 74. These projections on the oil circuit breakers may extend circularly around the same, or 70 may only extend part way. Supporting beams such as 964 and 965 are engaged by the projecting brackets 962 and 963 of the oil circuit breakers. These supporting bars 964 and 965 extend, as shown in Figures 72 and 73, longitudinally 75 within a bay and between two of the tubular

elevators such as 959 and 960 on one side of the circuit breakers and corresponding elevators on the other side, respectively. The supporting beams are engaged by hook-like projections on the tubular elevators such as indicated by the reference numerals 966 and 967 in Figure 74. Transverse or cross supports such as 968 and 969 are also attached to the tubular elevators by means of projections thereon which are integral with the elevators as shown.

10 The oil circuit breakers 970, 971, and 972 are, as shown in the Figures 72 to 74, inclusive, held in operating position, resting on the supports such as 964 and 965 which in turn are supported by the tubular elevators as explained. Reference 15 numeral 973 indicates the control mechanism. The terminals of the oil circuit breakers are indicated by the reference numerals 974—975, 976—977, and 978—979. These terminals project through the recessed portion 980 on the supporting plate 902 and connect with the corresponding equipment located in the junction boxes support- 20 ed in the overhead position.

When it is desired to disconnect the oil circuit breakers from connection with the switching 25 equipment, it is merely necessary to close the circuit for the motor 947 which will operate the worm gear housed in the casing 945 and thereby 30 actuate the shafts 944 and 938 which, in turn, will actuate the shafts 908 and 909, respectively, 35 to operate the elevating screws which support the tubular elevators. These elevators will be lowered and will thereby lower the oil circuit breakers, acting also as guides for the circuit breakers. This operation may be accomplished by remote control from the switch house. Since the 40 elevator mechanism is individual to a bay, it is possible to actuate any number of elevators in the above member.

There are, generally speaking, three positions to 45 which it may be desirable to lower the oil circuit breakers. It may be necessary for certain reasons to disconnect the circuit breakers from the circuit. This entails merely a lowering of the circuit breakers to a position when the terminals 50 disengage from the corresponding switching equipment. Since this can be accomplished by the elevator mechanism, special disconnect switches are eliminated. It may be desirable to inspect the tank in this disconnect position. If 55 this is the case, it will be necessary to support the lid of the tank (after removing the screws which hold the lid to the tank) and to lower the tank further down. If removal of the oil circuit breaker from the switch gear is desired, 60 further lowering of the entire apparatus will be necessary. These three positions are particularly illustrated in the Figures 75, 76, and 77, which I will describe next.

The views shown in Figures 75 to 77, inclusive, 65 correspond to the view of the mechanism as shown in Figure 74. I have applied the same reference numerals to the Figures 75, 76, and 77, and shall explain only those parts in detail which differ from the structure shown in the previous figure, or which are necessary for explaining the 70 operation.

Referring now to the Figures 75, 76, and 77, which, it will be remembered, correspond to the view of the equipment as shown in Figure 74, it will be 75 seen that I have provided a slightly different drive from the one explained in connection with the previously described structure. Instead of employing a belt drive between the motor and the worm gear, I have shown the motor 947 mount- 75

ed on the support 948' which, in turn, is mounted on the longitudinally extending support 903. This motor is directly coupled to shafts which extend to worm gears such as 945'. There are two such worm gears provided, and each is directly coupled by means of a coupling such as 999 to its corresponding transverse shaft such as the shaft 908. This structure is also shown particularly in the Figures 78, 79, and 80 which will be described later in detail.

10 The motor 947' is, as was the case previously, reversible and operates the shafts such as 908 in either direction for elevating or lowering the tubular elevators such as 960 and 961 supported by the screws such as 933 and 934. The mounting of the shaft such as 908 in the bearings 906 and 907, as well as the operation of the screws 933 and 934 by means of the bevel gears is the same as was previously described and the corresponding explanations may be referred to for structural and functional details not mentioned in connection with Figures 75, 76, 77 and other figures yet to be described.

25 The Figures 75 to 77, inclusive, bring out some of the details more clearly, for example, they show particularly how the supports 956 and 958 are pivotally mounted on the angular bracket projections of the U-shaped members 922 and 925 which are pivotally mounted on the shaft 908. It will also be seen that the supports 956 and 958 are provided at their ends with hooks 987 and 988.

35 The Figure 75 shows the mechanism with the oil circuit breaker in disconnect position. The terminals 979 and 978 are removed from contact with the corresponding switching equipment mounted in overhead position on the structural framework. Numeral 973 indicates the control mechanism for the oil circuit breaker. It will be seen from the Figure 75 that the oil circuit breaker 972 rests with its brackets 962 and 963 on the supports 954 and 955 which in turn engage the hook-like supporting projections 966 and 967 provided on the tubular elevators 960 and 961. The tubular elevators have been lowered by means of the gear and shaft mechanism as was described previously have guided and positioned the oil circuit breaker in the position shown in Figure 75. The operation may be accomplished by remote control and automatically. Several circuit breakers may be disconnected at the same time.

45 The lid 981 of the oil circuit breaker is attached to the tank by means of bolts and nuts not shown in the drawings. It will be seen that the lid is provided with laterally projecting ledges such as 989 and 990. Now, when it is desired to inspect the circuit breaker, a further lowering of the tank proper is necessary while the lid 981 must be supported during the lowering operation and during inspection.

55 The provisions holding the lid 981 to the tank of the oil circuit breaker, such as bolts and nuts, are removed when the oil circuit breaker is in the position shown in Figure 75. The supports 956 and 958 are then attached to the ledges 989 and 990 of the lid 981 by means of the hooks 987 and 988, by swinging the supports 956 and 958 (which are pivotally mounted on the brackets 953 and 954) into the position as shown in Figure 75 with the hooks 987 and 988 engaging these ledges. 70 The circuit breaker tank is then lowered further down into the inspection position as is shown in Figure 76, the screw elevators guiding the same. It will be seen from this figure that the hooks 987 and 988 of the supporting members 956 and 958 hold the lid 981 of the oil circuit breaker while

the tank has been lowered further down by means of the tubular elevators 960 and 961. The oil circuit breaker can now be inspected conveniently when the same is in the inspection position as shown in Figure 76, the contacts 982, 983, 985, and 986 being conveniently exposed for any work desired.

75 Reattachment of the oil circuit breaker from the inspection position shown in Figure 76 is equally simple. The motor 947' is simply operated in the reverse direction, actuating the corresponding shafts such as 908, which in turn operate the screws such as 933 and 934 and companion screws on the opposite side, so that the tubular elevators are operated in reverse direction, raising and guiding the oil circuit breakers into the position shown in Figure 75. The lid 981 may then be attached to the tank by means of the bolts and nuts and further upward motion of the elevators will move the oil circuit breaker and guide the same back into the operating position. Every step of the operation is power controlled and saves manual labor as well as time.

80 The removal position of the oil circuit breaker is shown in Figure 77. The circuit breaker is brought into the position shown in this figure by completely lowering the tubular elevators as shown, and positioning the oil circuit breaker on the truck 991 which is provided with rollers such as 992 and 993 movable transversely to the switch gear on rails such as 994. The rails 994 are mounted on a platform 995 which is movable longitudinally to the switch gear by means of rollers 996 engaging rails such as 997. The elevator screws are spread apart and the beams 964 and 955 are removed when the oil circuit breaker is positioned on the truck.

85 The views 78, 79, and 80 correspond to the views shown in Figures 72, 73, and 74, respectively. The elevating equipment shown in these figures is substantially the same as described in connection with the previous figures, with the exception of the mechanism for driving the elevators. Instead of providing a motor which operates a worm gear over a belt, as first described, I have provided a motor 947' which is mounted on a support 948' (also shown in side views, Figures 75 to 77, inclusive) which is directly coupled by means of a coupling 942' to a shaft 938' which is rotatable in bearings 937' and 941', and, on the other side, by means of the coupling 943' to the worm gear within the housing 951'. The shaft 938' is coupled to the worm gear within the housing 945' by means of the coupling 950'. The worm gears 945' and 951' operate corresponding shafts which are directly coupled to the shafts 909' and 908' by means of the couplings 999' and 998, respectively.

90 I, therefore, have provided in this modification of the elevating equipment two worm gears directly coupled with the motor shaft and directly coupled with the drive shafts 908' and 909' instead of the bevel gear drive and the belt drive shown in the previously described embodiment.

95 The operation of this latter equipment is substantially the same, that is, the motor 947' is reversible and adapted to operate the worm gears encased in the housing 945' and 951', respectively, in the corresponding direction. The operation is communicated directly to the shafts 908' and 909'. The tubular elevators such as 959' and 960' will, therefore, be simultaneously lowered or elevated according to the direction in which the motor 947' is operated. All of the details shown in Figures 78 to 80, inclusive, are the same

as already discussed in connection with the Figures 72 to 77, inclusive, and the corresponding description may be referred to for any details. I have applied in Figures 78 to 80, inclusive, 5 primed reference numerals which refer to corresponding parts designated by unprimed reference numerals in the previously discussed figures.

It will be appreciated that the feature of automatically guiding the circuit breakers by means 10 of the elevator screws is of particular value since it eliminates special provisions for guiding and time consuming labor.

One detail may be particularly seen in Figure 15 79 which I desire to mention specifically. It will be seen that I have shown a recessed portion 980' in the supporting plate. This recessed portion corresponds to the recessed portion 980 shown in previous figures but is particularly clearly shown in the Figure 79. It will be seen that the elevating equipment such as the worm gear housings 20 945' and 951' are attached to the structural framework on either side of the recessed portion of the same. This structure permits saving of space which would be otherwise impossible.

25 Each bay is shipped for installation completely assembled and with the novel elevating mechanism attached thereto. The elevating screws and the tubular elevators supported thereby are, it will be recalled, mounted on U-shaped brackets which are pivotally supported on the respective operating shafts. These screws and their tubular elevators are folded back and suitably fastened to the structural framework when the equipment is prepared for shipment. With reference to Figure 79, for example, the pairs of screws on each side of a bay, such as the screws 35 932' and 933' (as well as the companion screws on the opposite side), are folded toward the right and left, respectively, and attached to the framework in some suitable manner.

40 Referring now generally to the foregoing description of the switch gear and of the improvements incorporated therein, it will be seen that all the novel details disclosed in this case have 45 several points in common.

Specifically, the novel structures and improvements shown and described are characterized by structural simplicity; by adaptability to standardization and mass production and by ease of assembly. As a consequence, the equipment can be manufactured easier and cheaper; the installation cost and field work is simplified and rendered less expensive; maintenance is benefited, and reliability of operation is increased. 55 All these points result in better service at less cost than was possible in the past.

In view of the voluminous description necessitated by the many improvements which I have incorporated in the switch gear disclosed in this 60 case, I desire, in conclusion, to enumerate the improvements separately below, with reference to the drawings in which they may be found, so that the physical structure of the salient features of my invention may be easily recalled when 65 reading the appended claims.

The following features and improvements are incorporated:

A novel method and means for removing cables 70 at the current transformer boxes which permits connection and removal of the cables from either side of the current transformers adapting a bay unit to be employed either as a generator bay or as a feeder bay;

A novel structure showing the current transformer in the same plane with the cross con-

ductor and a modification of this structure showing the current transformer in a plane below the cross conductor the former structure simplifying a difficult box structure and saving space;

5 A novel method and means for terminating the cables at the ground level or at any desired point between ground and the structural framework;

The above features and improvements may be found in the Figures 1 to 7, inclusive, and elsewhere. 10

I have further disclosed several embodiments of novel bus couplings and novel bus enclosure couplings, showing a variety of novel features which may be particularly found with reference to the Figures 8 to 12, inclusive, and with reference 15 to the Figures 65 to 69, inclusive;

A novel way of insulating the column bases from the vertical pillars is shown in Figure 13 in detail. This feature, of course, is carried out generally throughout. Every one of the vertical 20 pillars of the structural framework is insulated from the column base providing a simple fault bus and protective system;

A novel cable entrance or pot head box is 25 particularly shown in Figures 44, 46, and 47. The novelty in connection with this cable entrance box resides in the casting having the supporting ears integral with the box structure, and further in the method and means for attaching the box to the supporting framework in insulated 30 relation therefrom;

A novel alignment joint has been disclosed in connection with the Figures 42 and 43. This novel alignment joint, it will be remembered, is used in various places in the general equipment; 35

A novel current transformer and junction box is disclosed in Figures 34 and 35. The novelty in connection with this current transformer and junction box resides, similarly to the novelty in the cable entrance box mentioned previously, in 40 the particular structure of the box casting and in the manner of attaching the same to the structural framework in insulated relation therefrom;

A novel bus connector is shown in Figures 36 and 37, and a novel T bus connector is shown 45 in Figures 38 and 39. These two novel connectors are employed in the novel current transformer junction box shown in Figures 34 and 35 and also in other places in the equipment;

A novel oil retaining housing is disclosed in detail in the Figures 40 and 41, and also incorporated at various places in the general arrangement; 50

A novel junction box is shown in Figures 30 and 31. This junction box as well as the previously mentioned cable entrance and junction boxes is new in the general shape of the casting and in the provision of the flanged entrance and exit tubings integral with the box; 55

A novel pot head connector is shown in Figures 60 55 to 59, inclusive. This pot head connector shown in these figures contains a number of novel features which may be found by referring to the above mentioned drawings and to the corresponding description; 65

A further feature of novelty which I have incorporated in this case resides in the parallel bus connector shown in Figures 63 and 64;

Another novel structure is shown in the bus connector for contact caps illustrated in Figures 70 49 and 50;

Another novel bus connector for contact caps is shown in Figures 51 and 52;

A novel right angle offset bus connector is represented in Figures 53 and 54. 75

A novel junction box for use in the reactor bay is illustrated in Figures 32 and 33;

Another novel pot head connector distinguishing from the one disclosed in Figures 55 to 59, 5 inclusive, is the pot head connector shown in Figures 60 to 62, inclusive;

Another novel bus connector for a contact cap is shown in Figures 70 and 71. This last bus connector distinguishes in some respects from the 10 one shown in Figures 51 and 52, while certain features of the same are common with the bus connector shown in Figures 51 and 52; and

A novel elevating mechanism is shown in Figures 72 to 80, inclusive, disclosing structures 15 which show many features of novelty as particularly described in the detailed description previously rendered.

It will be understood, of course, that I have 20 enumerated above, in a summarizing manner only the most obvious novel structures and features described previously in detail. All these novel features are designed with a view to simplifying production, assembly shipment and erection of a station as contemplated in this case, 25 e. g., a station of the unit type construction in which every bay is shipped and installed as a unit and joined with other bay units. The above summary is intended to assist the reader in recalling the structural details to mind, and to enable him to locate the drawings in which they are disclosed. It may be mentioned that I have 30 enumerated the various improvements in the order in which they occur in the detailed specification.

Modifications of the structures disclosed in this case may be devised by following what it teaches in general as well as in particular. I, therefore, do not desire to be limited, in applying the invention, to the precise forms and embodiments which 40 I have shown and described but only to the meaning and scope of the claims. In the claims which follow I have defined what I consider new in the art and what I desire to have protected.

I claim:

1. In metal clad switch gear of the class described, the combination of a structural framework comprising vertically disposed columns, supports mounted on said columns in overhead position, switching apparatus, bus conductors enclosed in individual tubular housings, and junction boxes disposed on said supports, means for terminating cables rising from underground conduits at a point on said framework appreciably below the supports mounted on said framework, 55 and conductors disposed within oil filled tubular housings for connecting said cable terminal means with said switching apparatus.

2. In metal clad switch gear of the class described having a structural framework and supports mounted thereon in overhead position for supporting switching equipment, the combination of cable entrance boxes for receiving cables terminating in said switchgear thru underground conduits, means for mounting said boxes on said framework at a level appreciably lower than said supports and means in said boxes for connecting said cables to said switchgear.

3. In a system of the class described, a housing disposed in overhead position, a cross conductor entering and leaving said housing in insulated relation therefrom, a current transformer within said housing, another cross conductor within said housing, and means for establishing connection between said cross conductors and

said current transformer from either side of said transformer.

4. In a system of the class described, oil circuit breakers disposed in overhead position, contacts therefor, a housing interposed between said contacts, a cross conductor connecting two of said circuit breakers thru said housing in insulated relation therefrom, another cross conductor, a current transformer within said housing disposed in a plane below said first cross conductor, and 10 interchangeable connector means for establishing connection between said cross conductors and said current transformer from either side thereof.

5. In a system of the class described, oil circuit breakers disposed in overhead position, contacts therefor, a housing interposed between two of said circuit breakers, a cross conductor connecting said contacts thru said housing in insulated relation therefrom, another cross conductor, a current transformer within said housing 20 disposed in the plane of said first cross conductor, and interchangeable connector means for establishing connection between said cross conductors and said current transformer from either side thereof.

6. In an electric bus and switch station, bus bars comprising sections, means including an intermediate bus section for joining said sections, bus enclosing tubing for said bus sections, tubular coupling means for coupling said tubing in 30 insulated relation from each other, expandable means in said tubular coupling means for permitting expansion and contraction of said coupled tubing, and means cooperating with said intermediate bus section for joining said tubular 35 coupling means in oil tight relation relative to said bus sections.

7. In a metal clad oil filled switch gear of the class described, bus bars comprising sections, bus enclosing tubing comprising sections, bus coupling means for conductively joining said bus sections, bus enclosure coupling means for joining said tubing sections in insulated relation from each other and in oil tight relation to each other, means cooperating with said bus enclosure coupling 40 for permitting expansion and contraction of said bus tubing, and means cooperating with said bus coupling and said bus enclosure coupling for preventing communication of oil from one bus section to the other bus section.

8. In a metal clad oil filled switch gear of the class described, a bus enclosure coupling for joining adjacent tubular bus enclosures containing bus conductors, comprising two tubular members 45 slideable upon said bus enclosures, means for attaching each member to the corresponding bus enclosure and in oil tight relation thereto, means for joining said members in oil tight relation and electrically insulated from each other, and means cooperating with one of said members for permitting expansion and contraction of said enclosures.

9. In a metal clad oil filled switch gear of the class described, a bus enclosure coupling for joining adjacent tubular bus enclosures containing bus conductors, comprising two tubular members 65 slideable upon said bus enclosures, means for attaching each member to the corresponding bus enclosure and in oil tight relation thereto, means for joining said members in oil tight relation and electrically insulated from each other, and oil 70 insulating means cooperating with said bus enclosure coupling and with the bus conductor therein for providing separate oil chambers extending from said coupling to the bus enclosures joined thereby.

10. In a metal clad oil filled switch gear of the class described, a bus enclosure coupling for joining adjacent tubular bus enclosures containing bus conductors, comprising two tubular members 5 slideable upon said bus enclosures, means for attaching each member to the corresponding bus enclosure and in oil tight relation thereto, means for joining said members in oil tight relation and electrically insulated from each other, means co-operating with one of said members for permitting expansion and contraction of said enclosures, and oil insulating means cooperating with said bus enclosure coupling and the bus conductor therein for providing separate oil chambers extending from said coupling to the bus enclosures joined thereby.
11. In a bus and switch station having a structural framework defining a plurality of bays, a cable entrance box, comprising a body, a flange thereon, a cover attached to said flange and removable therefrom, entrance and exit means for cables, mounting members on said body for attaching the same to said structural framework, and insulating means interposed between said mounting members and said framework for insulating said body from said framework.
12. In a metal clad oil filled switch gear comprising column bases disposed at the ground level, vertical supporting pillars disposed on said bases in insulated relation therefrom, a structural framework mounted on said pillars in overhead position, cable entrance boxes mounted laterally on said structure at points between the ground level and said framework in insulated relation therefrom and current transformer boxes mounted laterally on said structure in overhead position and insulated from said structure, a flanged tubing attached to each of said cable entrance boxes, a flanged alignment joint attached to each of said tubing, each alignment joint being attached at its other end to one of said current transformer boxes, a conductor enclosed within each of said tubing and said alignment joint, means within each of said cable entrance boxes for connecting said conductors to cable conductors, a current transformer within each of said current transformer boxes, connector means for establishing connection between said transformers and said enclosed conductors, a cross conductor leaving each of said current transformer boxes transversely to said overhead framework and in right angle to said first conductors, and connector means within said current transformer boxes for establishing connection therein between said cross conductors and said transformers, said cable entrance boxes, flanged tubings, alignment joints and current transformer boxes being joined in oil tight relation relative to each other.
13. In a metal clad switch gear of the class described, comprising a structural framework for supporting switching equipment in overhead position, a housing attached to said framework in insulated relation therefrom, a cover for said housing attached thereto in oil-tight relation, a tubular flanged projection integral with said housing and disposed at the bottom thereof, a tubular flanged projection integral with said housing and disposed in right angle to said first projection in the rear wall of said housing above said first projection, a transformer mounted within said housing, a conductor entering said housing thru said first projection, connector means for establishing connection between said conductor and said transformer, a conductor enter-
- ing said housing thru said second projection, and connector means for establishing connection between said second conductor and said transformer, each of said connector means comprising two separate clamp members for attaching said conductors to said transformer. 5
14. In a metal clad switch gear of the class described, comprising a structural framework for supporting switching equipment in overhead position, a current transformer box, a cover therefor, means for removably attaching said cover in oil-tight relation to said box, mounting means integral with said box, means cooperating with said mounting means for attaching said box in overhead position laterally to said framework and in insulated relation thereto, a flanged entrance tubing integral with said box disposed at the bottom thereof, and a flanged exit tubing integral with said box disposed in right angle to said entrance tubing and in the rear wall of said 10 box.
15. In a metal clad oil filled switch gear of the class described having a structural framework including supports mounted in overhead position, a first junction box mounted on said supports, 25 a bus bar extending therethrough, a second junction box attached to said first junction box in oil-tight relation thereto, a flanged flexible tubing attached to said second junction box in the same plane of attachment of said 30 second box to said first box, a conductor entering said second junction box from said first box, a conductor leaving said second junction box thru said flexible tubing attached thereto, a connector within said second junction box for establishing connection between said conductors, and a cover attached removably to said second junction box and in oil-tight relation thereto.
16. In insulated tubular bus sections disposed within tubular oil containing sheathing on a 40 structural framework comprising a plurality of unit fabricated bays and terminating at the edges of said bays, the combination of a coupling for joining adjacent bus sections, comprising a flexible conductor, clamping means for attaching 45 said conductor to said adjacent bus sections, insulating tubular sleeve means for attachment to said bus sections for covering said coupling, and means in said sleeve means for circulating oil thru said covered bus coupling. 50
17. In a metal clad switch gear of the class described including a plurality of unitary structural sections, having tubular oil containing bus enclosures provided in sections corresponding to said structural sections and supported in elevated 55 overhead position, a coupling for joining adjacent bus enclosure sections, comprising a first, a second and a third tubular member, means for joining said first and said second member in oil tight relation, a tubular insulating member provided with a flange, said member being slideable on said third tubular coupling member and slideable within said second tubular coupling member, an annular ridge provided within said second coupling member, packing means, means for attaching said tubular insulating member to said second coupling member with said packing means engaging said ridge and providing an oil tight joint between said second and said third coupling member, a tubular alignment joint attached 60 in oil tight relation to said third coupling member, a tubular housing attached to said alignment joint in oil tight relation thereto, means on said first coupling member and on said housing for attaching adjacent bus enclosure sections there- 65
- 70
- 75
- 75

- to, and means within said first coupling member and said housing for circulating oil thru said bus enclosure coupling.
18. In a metal clad oil-filled switch gear of the 5 class described, tubular oil containing bus enclosures provided in sections and enclosing bus conductors, a coupling for joining adjacent sections in insulated relation from each other and in oil tight relation to each other, alignment means in said coupling for permitting expansion and contraction of said sections relative to each other, means for circulating oil thru said coupling, and means for separating the oil circulation thru said adjacent sections from the oil circulation thru said coupling.
19. In a metal clad oil filled switch gear of the 10 class described, tubular oil containing bus enclosures provided in sections and enclosing bus conductors, a coupling for adjustably joining adjacent sections in electrically insulated relation from, and in oil tight relation to, each other, means in said coupling for adjusting and equalizing expansion and contraction of said adjacent sections, and adjustable, separate oil circulating means for said coupling and for said adjacent bus enclosure sections.
20. In a metal clad oil filled switch gear of the 15 class described, insulated bus conductors provided in sections, said conductors being disposed within bus enclosures provided in sections, a coupling for joining adjacent bus conductors having a flexible joint for permitting expansion and contraction of said coupled conductor sections, tubular insulating means for covering said bus conductor coupling, means in said tubular means for circulating oil thru said bus conductor coupling, a coupling disposed around said bus coupling for joining adjacent bus enclosure sections in electrically insulated relation and oil tight relative to each other, means in said bus enclosure coupling for equalizing expansion and contraction of said adjacent enclosure sections, and adjustable means for separating the oil circulation thru said bus enclosure coupling and said coupled bus enclosure sections.
21. In a system for transmitting electric power, 20 bus conductors provided in sections, said conductors being disposed within oil containing bus enclosures, means for conductively joining adjacent bus sections, separate independently removable means disposed around said bus joining means for joining said bus enclosures in oil tight relation and electrically insulated from each other, and means preventing leakage of oil from said bus enclosures upon joining or unjoining thereof.
22. In a system for transmitting electric power, 25 bus conductors provided in sections, said conductors being disposed within oil containing bus housings, means for conductively joining adjacent bus sections, separate means disposed independently and removably around said bus joining means and between said housings for joining said housings in oil tight relation and electrically insulated from each other, means in said separate means for equalizing expansion and contraction of said joined housings, and means for preventing leakage of oil from said bus housings upon joining or unjoining thereof.
23. In a system for transmitting electric power, 30 bus conductors provided in sections, said conductors being disposed within oil containing bus housings, means for conductively joining adjacent bus sections, separate means disposed independently and removably around said bus join-

ing means and between the ends of said housings for joining said housings in oil tight relation and electrically insulated from each other, means in said separate means for equalizing expansion and contraction of said joined housings, and means for separately circulating oil thru said housings and said separate coupling means joining said housings.

24. In a system for transmitting electric power, 35 bus conductors provided in sections, said conductors being disposed within oil containing housings, means for conductively joining adjacent bus sections, separate means disposed independently and removably around said bus joining means and between the ends of said housings for joining said housings in oil tight relation and electrically insulated from each other, means for equalizing expansion and contraction of said joined bus sections, means for equalizing expansion and contraction of said joined housings, and adjustable 40 means for separately circulating oil thru said joined housings and thru the means joining said housings.

25. In a cable entrance box for a system of metal clad switchgear having tubular conductors, 45 each conductor enclosed in a tubular metallic housing, a plurality of cables terminating in said box, a tubular conductor leaving said box and leading to switching equipment for said system, a connector attached to said conductor within said box, comprising two reversible clamp members each provided with a laterally extending arm, conductive links laterally connecting said cables within said box, and conductive, flexible links axially connecting said links and said laterally extending arms.

26. In a bus and switch station having a structural framework provided with overhead supports, a switching contact mounted on said overhead supports, a cap therefor, projections provided on 50 said cap, a plurality of flexible links attached to said projections, a bus conductor mounted on said overhead supports and disposed normal to said cap, a connector for establishing connection between said bus conductor and said cap by 55 means of said links, comprising a split clamp body firmly attached to said bus conductor, having laterally projecting angular arms, and means for fastening said links to said arms.

27. In a bus and switch station having a structural framework provided with overhead supports, 55 a bus conductor mounted on said overhead supports, switching means disposed in right angle to said conductor, a contact cap for said switching means, a connector for establishing connection 60 between said conductor and said contact cap, comprising a split clamp member for rigid attachment to said conductor, and flexible means for attachment to said clamp member and said contact cap.

28. In a bus and switch station, a structural framework, a circuit breaker mounted on said framework in overhead position, having a stationary contact cap provided with projections, a bus conductor mounted on said framework and 65 disposed at right angles to the axial plane of said contact cap, a connector attached to said bus conductor, comprising two members each provided at one end with projections registering with the projections on said contact cap, and each provided at its other end with registering companion clamp structures for attachment to said bus conductor, means for joining said members, means for firmly attaching said clamp structures to said bus conductor, and flexible means for joining said 70 75

registering projections on said members and on said contact cap.

29. In a bus and switch station comprising a structural supporting framework, a bus conductor supported thereby, a contact cap disposed in right angle to said conductor, a connector for establishing connection between said conductor and said contact cap, comprising two separate companion clamp members for attachment to said conductor, means for rigidly joining said members, and flexible means for joining said members to said contact cap.

30. In a bus and switch station of the class described having a structural framework provided with overhead supports, a junction box mounted on said overhead supports and having a body, a flange thereon, a cover attached to said flange in oil tight relation thereto, two flanged tubular extensions projecting from said box in opposite directions on the same axis, and a third flanged tubular extension projecting from said box in the same axial plane but in right angle to said other extensions, said flange and said tubular extensions being integral with said box.

31. In a bus and switch station, a structural framework, a switching contact supported from said framework in overhead position, a contact cap therefor mounted on said framework, a first bus conductor disposed above said contact cap in right angle to its axis, a second bus conductor disposed above said first conductor in right angle to its axis, and a connector for conductively interconnecting said contact cap and said first and second bus conductors, comprising a first clamp provision attached to said first conductor, a second clamp provision attached to said second conductor, and flexible link means connecting said first clamp provision with said contact cap and with said second clamp provision.

32. In a system for transmitting and for distributing electric power, a structural framework, a substantially stationary contact mounted on said framework, a substantially stationary conductor mounted on said framework above said contact, a cross-conductor adjacent to said contact and said conductor, and a connector comprising flexible braid for establishing connection between said cross conductor, said contact and said stationary conductor.

33. In a bus and switch station, a structural framework, a contact supported on said framework, a bus conductor disposed above said contact with its axis at right angles to the axis of said contact, a cross conductor disposed between said bus conductor and said contact with its axis at right angles to the axis of said bus conductor and substantially in the axial plane of said contact, connector means for bus conductor, connector means for said cross conductor, and flexible means for interconnecting said connector means and said contact.

34. In a bus and switch station, a structural framework having overhead supports, a circuit breaker supported therefrom, a stationary cast contact for said circuit breaker, a bus conductor mounted on said framework, a cast connector attached to said bus conductor, a cross conductor mounted on said framework and interposed between said contact and said bus conductor, a cast connector attached to said cross conductor, and flexible means for establishing connection between said cast connectors and said contact, said flexible means being rigidly bolted to said connectors and said contact.

35. In a system of the class described com-

prising a plurality of bays, the unit structure of a bay comprising a structural framework, oil-filled junction boxes supported thereon, buses enclosed in individual oil-filled sheathings disposed between said junction boxes longitudinally to said bay and extending substantially to the edge of said bays, means for retaining oil in said boxes and in said sheathings during shipment and erection of said bay, means for joining said buses and said sheathing with corresponding buses and sheathings of adjacent unit bays at the bay divisions, and means for adjustably establishing oil communication between sheathings of adjacent bays after said sheathings have been joined.

36. In a system of the class described comprising a plurality of bays, the unit structure of a bay comprising a structural framework, oil-filled junction boxes thereon, conductors enclosed in oil-filled sheathings disposed between said boxes transversely to said framework, buses enclosed in oil-filled sheathings disposed longitudinally to said framework, said bus sheathings being grounded to said framework, means for filling said boxes and said sheathings with oil, means for conductively joining said buses with corresponding buses of adjacent unit bays, expansible independently removable means for joining said bus sheathings of adjacent bays in insulated relation to each other, and means for preventing leakage of oil from said sheathings and said boxes during said joining operation.

37. In a system of the class described composed of a plurality of assembled bays and comprising unit bays, each of said bays including a structural framework supported on columns in overhead position, buses enclosed in oil-filled sheathings disposed on said framework and terminating substantially at the edge of said bay, sections of said sheathings being joined in insulated relation to each other at the bay divisions and grounded to said framework, a fault bus control and protective system comprising means for insulating said columns to ground, and means including transformers for disconnecting faulty bus sections grounded thru said sheathings.

38. In a system for transmitting electric energy, comprising a plurality of bay units, sectional buses disposed on sectional oil-filled sheathings extending longitudinally of said units, means for joining said buses at the bay divisions, and means for joining said sheathings at the bay divisions, each of said last means comprising a coupling for joining adjacent sheathings in insulated relation but oil tight relative to each other, adjustable means for regulating and at will inhibiting the flow of oil from one section of said sheathing to the other, and expansible means for permitting expansion and contraction of said adjacent sheathings relative to each other.

39. In combination, in a unit bay adapted to be aligned with and connected to other similar bays to form a sectionalized metal clad switch gear, a structural overhead framework carried on said bay, bus conductors extending transversely and longitudinally of said framework, junction boxes enclosing the joined ends of said conductors, and clamping means for maintaining said conductors in normal alignment and for electrically connecting the same, comprising two separate clamp members, each having two clamp sections disposed at right angles and adapted to engage about the ends of said conductors, and means for joining said clamp members.

40. In combination, cable entrance means supported on a structural framework, a plurality of cables terminating in a single plane within said entrance means, a bus conductor supported on said framework above said cable entrance means, and connector means disposed within said cable entrance means for establishing connection between said bus conductor and said cable, comprising individual contact stud means attached to said cables, a pair of rigid contact blades disposed in parallel and connecting said stud means, a connector having two arms projecting laterally in parallel attached to said bus conductor, and flexible means for connecting said parallel blade means with said parallel arms.

41. In metal clad switch gear, a structural framework having overhead supports, a circuit breaker suspended therefrom, stationary cast contacts for said circuit breaker, a bus conductor mounted on said framework, a cast connector attached to said bus conductor, a cross conductor mounted on said framework and interposed between said contact and said bus conductor, a cast connector attached to said cross conductor, and flexible means for establishing connection between said cast connectors and said contacts.

42. In combination, a unit bay adapted to form one section of a sectionalized metal clad switch gear, said bay including a structural framework, a plurality of bus conductors disposed within oil-filled sheathings on said framework, said sheathings terminating at the edge of said bay and having stopper means therein for centering said conductors and for preventing the flow of oil to either side thereof, and tubular means carried by said stopper means and extending axially thereof for insulating said conductors relative to said sheathings.

43. A metal clad bus and switch station consisting of a plurality of unit bays, each of said bays comprising a structural framework on which are supported in elevated position oil filled junction boxes, circuit breakers, sectional buses enclosed in sectional oil filled sheathings disposed between said junction boxes and extending to the bay divisions, means for joining said buses and sheathings with those of adjacent bays, means for retaining oil in said boxes and in said sheathings during shipment and installation of said unit bay, and means providing for the free circulation of the oil between said boxes and said sheathings of neighboring bays after assembly.

44. In combination, in a unit bay adapted to be aligned with and connected to other similar bays to form a metal-clad switching station, a structural framework provided with overhead supports, a plurality of bus conductors mounted on said overhead supports, each of said bus conductors having a contact cap conductively connected thereto, said caps being mounted in insulated relation on said overhead supports, a set of inter-related circuit breakers, each breaker having a slip connector adapted for making contact with one of said contact caps respectively, a common supporting structure for said inter-related circuit breakers, and means comprising power operated screws, individual to said set of circuit breakers and adapted to engage said common supporting structure, for suspending said circuit breakers from said structural framework, for raising said circuit breakers into contact with said contact caps, and for lowering said circuit breakers

ers to disconnect said slip connectors from said contact caps.

45. In combination, in a unit bay adapted to be aligned with and connected to other similar bays to form a metal clad switching station, a structural framework provided with overhead supports, a polyphase bus comprising separate phase conductors, each conductor being enclosed in an individual metallic housing mounted on said overhead supports, each of said bus conductors having a contact cap conductively connected thereto and disposed within said housing, a set of circuit breakers, one breaker for each phase of said bus, each of said breakers having a slip connector adapted for making contact with one of said contact caps respectively, a common supporting structure for said circuit breakers, and means comprising power operated screws, individual to said set of circuit breakers, said screws being adapted to engage said common supporting structure, for suspending said circuit breakers from said structural framework, for raising said circuit breakers into contact with said contact caps, and for lowering said circuit breakers to disconnect said slip connectors from said contact caps.

46. In combination, in a unit bay adapted to be aligned with and connected to other similar bays to form a metal clad switching station, a structural framework provided with overhead supports, two polyphase buses, each bus comprising separate phase conductors, each of said conductors being enclosed in an individual metallic housing mounted on said overhead supports, each of said bus conductors having a contact cap conductively connected thereto and disposed within said housing, a set of circuit breakers for each of said buses respectively, one circuit breaker for each phase of each bus, each of said breakers having a slip connector adapted for making contact with one of said contact caps respectively, a common supporting structure for each of said sets of circuit breakers respectively, and means comprising a set of power operated screws individual to each of said sets of circuit breakers, said screws being adapted to engage said common supporting structure, for suspending said circuit breakers from said structural framework, for raising said circuit breakers into contact with said contact caps, and for lowering said circuit breakers to disconnect said slip connectors from said contact caps.

47. In a metal clad bus and switch station a unit bay comprising in combination, a structural framework provided with overhead supports, a plurality of bus conductors mounted on said overhead supports, each of said bus conductors having a contact cap conductively connected thereto, said caps being mounted in insulated relation on said overhead supports, a set of inter-related circuit breakers, each breaker having a slip connector adapted for making contact with one of said contact caps respectively, a common supporting structure for said inter-related circuit breakers, and four elevating screws, one of said screws engaging and supporting each corner of said supporting structure, for suspending said circuit breakers from said structural framework, for raising said circuit breakers into contact with said contact caps, and for lowering said circuit breakers to disconnect said slip connectors from said contact caps.
